JOHN WICKS, OF OAK PARK, ILLINOIS, ASSIGNOR TO RESERVE HOLDING COMPANY, OF CHICAGO, ILLINOIS, A CORPORATION OF DELAWARE

TELEPHONE SYSTEM

Application filed January 7, 1927. Serial No. 159,525.

This invention relates in general to automatic telephone systems; and the object of the invention, broadly stated, is the provision of new and improved automatic switching mechanism and controlling apparatus for use 5 in an automatic telephone exchange.

Two well known types of automatic switches are at present extensively used in automatic telephone exchange system; one 10 type being the well known Strowger vertical and rotary type of switch, and the other the well known rotary type of switch having a forward motion in only one direction. The Strowger vertical and rotary type of switches 15 are used as directive switches, that is, as selectors and connectors. The uni-directional rotary type of switches, however, in the main, are used only as hunting or pre-selecting switches, such as primary or secondary line 20 switches. In the past, automatic telephone exchanges equipped with Strowger type directive switches and rotary type preselecting switches have been proven to be most economical and reliable from every point of con- 25 sideration.

However, the uni-directional rotary switch mechanism, having a single motor magnet, is 30 recognized as being a very rugged and comparatively inexpensive mechanism, much less 35 expensive than the two-motion switch mechanism of the Strowger type having two motor magnets and a release magnet. The rotary switch mechanism may also be operated safely at much higher speeds than the Strowger 40 two-motion type of switch. The main object 45 of this invention, specifically stated, is the production of an automatic telephone system in which all the switches are of the uni-directional rotary type, the directive switches, that 50 is the selectors and connectors, as well as the hunting or preselecting switches.

The principal advantages of a system of this kind are; first, the reduced cost of the 55 exchange apparatus, since uni-directional rotary switches are less expensive than two-motion Strowger switches; secondly, the maintenance of the exchange apparatus is simplified and as a result the cost thereof is reduced by the employment of just one kind 60 of switch throughout the exchange. Another

advantage is that a call may be extended from calling to called subscribers more quickly, thereby reducing the amount of equipment required in any given case.

Another object of this invention is the production of a new and improved register sender for controlling the operation of the new and improved uni-directional automatic switches, the particular method of control being such as to permit the control circuits 55 of the new automatic switches to be very simple and reliable.

The invention, its features and operation will be described in detail in the following specification with the aid of the accompanying drawings comprising Figs. 1-8, inclusive. Figs. 1-5, inclusive, when arranged as shown in Fig. 8 with the corresponding lines in alignment, show by means of the usual schematic circuit diagrams the new and improved selector, connector, reverting call switch, and register sender, and sufficient of the associated apparatus for rendering possible a thorough understanding of the invention. In Fig. 6, a modification of the selector 60 and of the connector are shown. In Fig. 7, the grouping of the banks of the new switches is diagrammatically shown.

In Fig. 1 of the drawings, the subscriber's line comprising conductors 2 and 3 serves the sub-stations A'-A¹⁰, inclusive, and terminates at the main automatic exchange in the rotary lineswitch LS. The substations A'-A¹⁰ are of the usual automatic type with ringers connected from either one or the other side of the line to ground, and the lineswitch LS is of the well known rotary type of non-numerical selecting switch having no normal position and having a forward motion in only one direction. The lineswitch LS together with other similar lineswitches have access in their banks to a group of trunk lines, one of which is shown comprising conductors 22-25, inclusive, with its associated trunk relay group TRG and its individual 85 register sender selector RSS, terminating in the first selector switch S'.

Mechanically and in principle of operation, the register sender selector RSS is of the well known rotary type of non-numerical selecting 90 95 100

- switch having no normal position and having a forward motion in only one direction. In the banks of the register sender selector RSS, as well as in the banks of other similar 5 register sender selectors multiply connected with the banks of the register sender selector RSS, access is had to a group of register senders, one of which is shown in Figs. 2 and 3 combined, designated RS.
- 10 The register sender shown in Figs. 2 and 3 comprises essentially four digit registers upon which the line designating digits of a called number are registered, sequence switch S for controlling the operation of the digit 15 registers, sequence switch SS for successively associating the registers with the circuits for controlling the operation of the directive switches, a frequency selecting switch FS for selecting the proper frequency of ringing current to be applied to a called line (as determined by the last digit of a called number), a group of two-step counting relays for controlling the application of ground potential to the ten marking conductors of the digit 20 registers, and the various controlling relays. The conductors 576'-580', inclusive, connected to the lower bank contacts of the frequency selecting switch FS, are connected to the correspondingly marked conductors 25 shown in Fig. 5 connected to the five ringing generators G'-G⁵. A common interrupter I which periodically grounds conductor 200 momentarily is also shown in Fig. 2. The function thereof will be described 30 hereinafter.

The various sequence switches and registers of the register sender are of the well known single motion type of switch having a motor magnet for stepping the switch wipers in a 40 forward direction and a release magnet for returning the switch wipers to normal.

Mechanically, the switch mechanism of the selector S' is similar to the switch mechanism of the common rotary lineswitch, except that it has been provided with two sets of single-ended multiply connected wipers mounted on the same shaft, wipers 131, 133, and 135 being one set and wipers 132, 134, and 136 being the other set, and a separate 45 set of banks for each set of wipers, the two sets of banks being placed side-by-side. The two sets of wipers are positioned on the shaft 180 degrees apart, so that when one set of wipers is moved off the last set of contacts of its associated set of banks, the other set of wipers is moved onto the first set of contacts in its associated set of banks.

The bank contact grouping of a selector S' is shown more in detail diagrammatically 50 in Fig. 7, to which reference is now made. In each set of banks of the selector, access is had to five groups of trunks of ten trunks each, groups 0, 1, 2, 3, and 4 being accessible in the set of banks associated with wipers 131, 133, and 135, and groups 5, 6, 7, 8, and 9 being ac-

cessible in the set of banks associated with wipers 132, 134, and 136, in the order named. (Only wiper 131 of one set, and wiper 132 of the other set and the bank contact of each set associated with these two wipers, are shown in Fig. 7.) Each group of contacts comprises 55 70 75 11 sets. The ten trunks of a group are respectively accessible in the first ten sets of contacts of the corresponding group. The eleventh set of each group is the over-flow position, to which the wipers are moved when all the trunks of the corresponding group test busy, as is described in detail hereinafter. The shaft upon which the switches are mounted, also carries two cams, namely cams 121 and 120. Cam 121 controls the cam springs 124, and has recesses on its circumference so spaced that the springs 124 are closed whenever either set of wipers is in engagement with the last five sets of contacts of any group, these springs opening as the wipers are moved onto the first set of contacts of the succeeding group. Cam 120 controls the cam springs 122 and 123, and has one recess, maintaining springs 122 and 123 closed in all 80 85 90 95 positions of the switch wipers except when wipers 131, 133, and 135 come in engagement with the first set of contacts of group 0. The functions of these cam springs are described in the detailed description of the operation of the selector given hereinafter.

The control circuits of the selector form a particular part of the invention, and will be described in detail in later paragraphs.

One of the trunks, accessible in the third 100 group of bank contacts of selector S', and in the third group of bank contacts of the other similar selectors multiply connected therewith, is shown, comprising conductors 142, 143, and 144 terminating in the second selector S², Fig. 4. The second selector S² is 105 identical in circuit operation and also in mechanical construction to the first selector S' shown in Fig. 1. In the banks of the selector S², as well as in the banks of other similar second selectors multiply connected with the banks of the second selector S², access is had to a number of groups of connector switches. The connector C shown is accessible 110 in the seventh group of bank contacts by way of the trunk comprising conductors 452-454, inclusive. In the banks of the second selectors, access is also had to a group of trunks extending to an operator's position, and to a group of trunks extending to 115 reverting call switches. The trunks to the operator's position are accessible in the second group of contacts, one of which is shown comprising conductors 437-439, inclusive, and terminating in jack J. The trunk to the reverting call switches are accessible 120 in the first group of contacts, one of which is shown comprising conductors 442-444, inclusive, and terminating in the reverting call switch RV Fig. 5. 125 130

Mechanically the connector C is similar to the selector S', and has the same wiper and bank construction. In the banks of the connectors, the first set of contacts in each group 5 is unequipped and the ten subscribers' lines of a group terminate, respectively, in the next ten sets of contacts of a group, differing in this respect from the bank connections of the selectors in which the first ten sets of contacts of each group terminate trunks and the eleventh set is unequipped. The control circuits of the connector C form a particular part of this invention and will be described in detail hereinafter.

10 The subscribers' lines accessible in the banks of the connectors may be either individual lines or party lines, the party line comprising conductors 492 and 494 and serving the substations B¹—B¹⁰, inclusive, and provided with the individual lineswitch LS', being shown. The lineswitch LS' is similar to the lineswitch shown in Fig. 1 except that the wiper for controlling the operation of a completed-call meter has been omitted. The 15 substations B¹—B¹⁰ are identical to the substations A'—A¹⁰, inclusive, shown in Fig. 1.

Mechanically, the reverting call switch RV shown in Fig. 5 is also similar to the connector C. The control circuits of the reverting 20 call switch form a part of this invention and will be described hereinafter. The bank contacts of the reverting call switch are grouped like those of the connector C, and together with the bank contacts of the other reverting call connector multiple connected therewith are connected in various combinations to the ringing generators G¹—G⁵, inclusive, and the interrupter I⁵.

In the drawing, connections for signalling 25 two subscribers whose ringers are connected to one side of the line, two subscribers whose ringers are connected to the other side of the line, two subscribers whose ringers are connected to opposite sides of the line and respond to the same frequency of ringing current, and two subscribers whose ringers are connected to opposite sides of the line and respond to different frequencies of ringing current, are shown for illustration. It is understood that the five ringing generators G¹—G⁵ 30 are all of different frequencies and that the ringers at the party-line substations respond to only one frequency of ringing current. For explanatory purposes, it has been assumed that the ringers at the respective party-line substations A' to A⁵, A⁶ to A¹⁰, B¹ to B⁵, and B⁶ to B¹⁰ respond to ringing current from the respective generators G¹—G⁵.

35 With this general description of the objects of the invention, its features, and the apparatus used, in mind, a further understanding and appreciation of the invention may be gained from a detailed description of the operations performed in the establishment of various connections. For this purpose it

will first be assumed that the subscriber at substation A⁵ wishes to establish a connection with the subscriber at substation B⁵.

Call from substation A⁵ to substation B⁵

To establish a connection with the subscriber at substation B⁵, the subscriber at substation A⁵ first removes his receiver. Removing the receiver at substation A⁵ places a bridge across the line conductors 2 and 3, thereby closing a circuit for line relay 6 of the lineswitch LS. Line relay 6 operates and places ground potential on the private normal conductor 3 at armature 12 to mark the line to substations A'—A¹⁰ busy and at the same time to prepare an energizing circuit for switching relay 5. At armature 13, line relay 6 closes the stepping circuit for magnet 7, providing the trunk upon which the switch wipers are positioned at this time is busy, in which case ground potential will be present on the contact engaged by test wiper 15. If such is the case, stepping magnet 7 operates in a buzzer-like manner to advance the switch wipers 14—17, inclusive, in search of an idle trunk. During this operation switching relay 5 is prevented from operating by reason of the ground potential on both ends of its winding.

When an idle trunk is reached, indicated by the absence of ground potential on the contact engaged by test wiper 15, stepping magnet 7 ceases to operate, and relay 5, being no longer short circuited, energizes in series with magnet 7. In operating, relay 5 prepares a circuit for the subscriber's meter M at armature 10, prepares a holding circuit for itself at armature 9, and at armatures 8 and 11 disconnects the line conductors from the line relay 6 and ground, and extends the talking connection by way of these armatures and their working contacts, wipers 14 and 17, conductors 22 and 25, normally closed contacts 59' and 62' controlled by armatures 59 and 62, through the upper and lower windings of line relay 31 to battery and ground, respectively. Line relay 31 operates and closes a circuit for release relay 32 at armature 41. Release relay 32 energizes and grounds the release conductor 23 at armature 42 thereby maintaining relay 5 operated, closes a circuit for the switching relay 72 of the register sender selector RSS in series with the lower winding of relay 34 and magnet 71 at armature 44, and at armature 41 closes the stepping circuit for magnet 71, at the same time short circuiting switching relay 72, providing the wipers of the register sender selector RSS are in engagement with the bank contacts associated with a busy 100 register sender, in which case ground potential is present on the bank contact engaged by test wipers 85. If such is the case, magnet 71 operates in a buzzer-like manner to advance the wipers 84—87, inclusive, until an 105 110 115 120 125 130

- idle register sender is reached, which may be assumed to be the one accessible by way of the conductors 94-97, inclusive. When this register sender is connected with, its idle condition being indicated by the absence of ground potential on conductor 95 connected to bank contact now engaged by wiper 85, magnet 71 ceases to operate and the short circuit is removed from switching relay 72. 5
- 10 The switching relay 72 then operates to perform the following circuit changes: At armature 74 the impulsing circuit over which the digits of the called number are to be sent to the register sender is prepared. At armature 75 ground potential through the lower winding of relay 34 of the trunk relay group TRG is placed on the test contact to which conductor 95 is connected and on the test contacts of the other register sender selectors 15
- 20 multiply connected therewith to mark the register sender in question busy, at the same time closing a circuit for release relay 206 of the register sender in series with relay 34. Release relay 206 operates and opens a point 25 in the circuit of release magnets 381-387, inclusive, at armature 222, at the same time grounding locking conductor 263 and 261 by way of armature 226 and its resting contact, and prepares a circuit at armature 220 for the time impulse relay 240 to be described more in detail later. Insufficient current flows in this circuit at this time to cause the operation of relay 34, relay 206 having a comparatively high resistance winding. As 30
- 35 a further result of the operation of relay 72, the bridge to be placed across the outgoing conductors 102 and 104 is prepared at armatures 76 and 77.
- The foregoing operations all take place in 40 a comparatively short time responsive to the removal of the receiver at the calling substation. After removing the receiver, the calling subscriber at substation A⁵ dials the directory number of the called subscriber, which for the sake of example, will be assumed to be 27085. Responsive to the dialling of the first digit 2, line relay 31 of the trunk relay group TRG operates in the usual manner and closes the impulsing circuit a 45 corresponding number of times, this circuit extending from ground at armature 41 and the resting contact, armature 43, armature 74, wiper 84, conductor 94, armature 212 and the resting contact, conductor 252, armature 50 308 and the resting contact, wipers 311 of the sequence switch S in engagement with its first bank contact, winding of stepping magnet 320 of the first digit register to battery. Stepping magnet 320 responds a corresponding 55 number of times and steps the switch wipers 324 and 325 into engagement with the second contacts of their respective banks. By the movement of wipers 324 and 325 off their normal position, off-normal springs 391 and 60 391' are closed. The circuits including these
- springs will be described later. Slow-acting relay 301 operates in multiple with the magnet 320 and at armature 305 closes the circuit for the slow-acting relay 302, which likewise operates. The slow-acting relay 312 also 70 operates in multiple with magnet 320, the function of which will become obvious from descriptions to be given presently.
- At the termination of this series of impulses, relay 301 deenergizes and breaks the circuit of relay 302. Relay 302, being slow-acting, maintains its armatures operated for a moment after its circuit is opened, and as a result a circuit is momentarily established for stepping magnet 310 of the sequence switch S, this circuit including armature 306 and the working contact, and armatures 304 and the resting contact. Magnet 310 operates and steps the wiper 311 into engagement with its second bank contact. Slow acting relay 312 also falls back at the termination of this first series of impulses and closes a start circuit for causing the operation of the first selector switch terminating the seized trunk line. For convenience, however, the description of this operation will be deferred until later. Wiper 311 on moving into its second position, shifts the incoming impulsing circuit from the stepping magnet 320 of the first digit register to the stepping magnet 321 of the second digit register, thereby preparing the second register to receive the next series of impulses. 80
- Responsive to the dialing of the next digit 7, line relay 31 again operates and this time 90 closes the impulsing circuit now including stepping magnet 321 of the second digit register a corresponding number of times. Stepping magnet 321 operates responsive thereto and steps the wipers 326 and 327 into engagement with the corresponding contacts of their respective banks. Slow-acting relay 313 operates in multiple with magnet 321, the function of which is similar to the function of relay 312 and will also be described 95 later. Relay 301 again operates during the impulsing period, this time in multiple with magnet 321 and again closes a circuit for energizing relay 302, these two relays again functioning to momentarily close the circuit of stepping magnet 310 at the termination 100 of this second series of impulses. Wiper 311 is then stepped into engagement with its third bank contact, thereby shifting the impulsing circuit so as to include the stepping magnet 322 of the third digit register, and disconnect magnet 321 of the second digit register. 105
- The third digit 0 as dialed by the calling subscriber is then energized on the third digit 110 register, wiper 328 being stepped to the corresponding contact in its bank by the operation of stepping magnet 322, after which wiper 311 is stepped into engagement with its fourth bank contact to shift the impulsing 120 circuit to the fourth digit register. 115
- 125
- 130

circuit from magnet 322 to magnet 323 of the fourth digit register. The fourth digit 8 is registered on the fourth digit register, wiper 329 being stepped into engagement with the corresponding bank contact in its bank by 5 the operation of magnet 323, after which wiper 311 is stepped into engagement with its fifth bank contact. Wiper 311, in being stepped to its fifth position, shifts the impulsing circuit from the stepping magnet 323 to 10 the stepping magnet 341 of the frequency selecting switch FS, thereby preparing for the registration of the final digit, which determines the frequency of ringing current and the side of the line to which it is to be applied to signal the desired party. Responsive 15 to the dialing of the final digit 5, magnet 331 operates to step the switch wipers 342 and 344 into engagement with the fifth contact in their respective banks. By the engagement 20 of wiper 343 with the fifth contact in its bank, to which the conductor 80' associated with ringing generator G⁵, Fig. 5, is connected, the frequency of ringing current to be used is determined. Furthermore, since ground 25 potential is connected to the first five contacts in the bank of wiper 342, a circuit is now closed for reversing relay 202. This relay, in operating, determines that the selected 30 ringing current is to be applied to that side of the called line that will be connected to upper talking conductor extending through the automatic switches.

This completes the description of the registration of the digits of the called number on the registers of the register sender. During the time that this is taking place, however, the call is being extended by the operation of automatic switches controlled by the setting of the registers, and a description of the operation thereof will now be given. It will be remembered that at the termination of the dialing of the first digit, slow acting relay 312 deenergizes. As a result, a circuit is closed 45 which may be traced from ground by way of the resting contact and armature 316, off-normal springs 391' closed upon the first step of wipers 324 and 325, wiper 346 of sequence switch S' in engagement with its first bank 50 contact, conductor 256, through the winding of start relay 209 to battery. The relay 209 operates and closes a bridge across the trunk conductors 102 and 104, thereby closing the control circuit for controlling the operation 55 of selector S' which may be traced from ground by way of the resting contact and armature 109 of selector S', conductor 22', armature 57 and the resting contact, armature 51 and the resting contact, armature 77, 60 wiper 87, conductor 97, armature 230 and the resting contact, armature 224, through the winding of impulsing relay 207, armature 229, resting contact and armature 231, conductor 96, wiper 86, armature 76, resting contact 65 tact and armature 58, resting contact and armature 62, conductor 25', armature 111 and the resting contact, resting contact and armature 118, through the winding of line relay 106 of selector S' to battery. Impulsing relay 207 of the register sender operates and at armature 223 places ground potential on conductor 260, thereby closing a circuit for the upper winding of the two-step relay 351. Relay 351 operates in its first step, causing armature 371 to engage its working contact, 70 thereby closing the circuit to grounded conductor 261 for operating this relay in its second step, this being prevented at this time by reason of its lower winding being short circuited. In the selector S', the line relay 106 75 also operates when the control circuit is closed by the operation of start relay 209. Relay 106, in operating, closes a circuit for release relay 107 at armature 112, there being ground potential on release conductor 23, and shunts armature 118 at armature 113 and the working contact. Release relay 107 operates and closes a locking circuit for itself to release conductor 23 at armature 117, and opens a point in the initial energizing circuit of line 80 relay 106 at armature 118, this armature however having been shunted by the operation of armature 113 of relay 106. At armature 119 a circuit is prepared which will be described 85 presently. As a further result of the operation of line relay 106, a self-interrupting circuit for stepping magnet 108 is closed at armature 114 and the working contact, and at armature 115 a circuit for sending impulses to (short circuiting) the impulsing relay 207 90 in the register sender is prepared. Stepping magnet 108 now operates and continues to operate in a buzzer-like manner and rotates the switch wipers step-by-step over the bank contacts as long as the control circuit is closed. 95 As the switch wipers 131, 133, and 135 come into engagement with the sixth set of contacts of the 0 group (see Fig. 7), the cam 121 secured to, and rotating with, the shaft carrying the wipers closes contacts 124, thus short 100 circuiting the impulsing relay 207 of the register sender and at the same time closing a local holding circuit for line relay 106. The impulsing relay 207 in the register sender 105 thereupon deenergizes and by releasing its armature 223 removes the short circuit from the lower winding of the two-step relay 351. This relay thereupon operates to its second step, operating all its armatures their full stroke. Relay 351, in operating to its second step, connects conductor 260 to the second marking relay 352 at armature 356, and at armature 361 connects ground potential to marking conductor 331 connected to the first 110 contacts in the lower banks of the digit registers by way of armatures 365, 364, 363, and 362 and their respective resting contacts. 115 Rotary magnet 108 continues to operate, and when the switch wipers 131, 133, and 135 come into engagement with the first set of 120 125 130

contacts of group "1", the cam springs 124 are again opened. As a result, the short circuit around the impulsing relay 207 of the register sender is removed, and this relay again operates in series with line relay 106 of the selector S'. The relay 207, in operating, again connects ground potential to conductor 260 which causes the operation of the second marking relay 352 in its first step, operating only armature 372. The switch wipers of the selector S' continue to rotate over the contacts of group "1" under the action of the rotary magnet 108, and again a local circuit is closed for line relay 106 of selector S' and relay 207 of the register sender is short circuited when the switch wipers are rotated over the last five contacts in group "1" by the closure of springs 124 under the control of cam 121. As soon as this relay is short circuited, it again deenergizes and permits the second marking relay 352 to operate in its second step, which in so doing connects conductor 260 to the upper winding of the third marking conductor relay 353 at armature 357, causes the restoration of the first marking relay 351 by opening its circuit to the grounded conductor 261 at armature 377, and at armature 362 disconnects ground from the first marking conductor 331 and connects it to the second marking conductor 332 connected to the second contacts in the lower banks of the digit registers. It will be remembered that wiper 325 is in engagement with the second contact in its bank connected to marking conductor 332. Therefore, as soon as ground potential is connected to this marking conductor, a circuit is closed which may be traced from ground on conductor 332, wiper 325 in engagement with its second bank contact, wiper 347 in engagement with its first bank contact, conductor 257, through the winding of stop relay 208 to battery. Relay 208 operates and opens the control circuit at armature 224, closes a circuit for relay 204 at armature 225, the function of which will be described later, and at armature 226 disconnects ground from conductor 261 thereby opening the circuit of the marking relay 352, which thereupon restores to normal. Furthermore, by the operation of relay 208 a circuit is closed for stepping magnet 345 at armature 227. This magnet energizes and in so doing moves the switch wipers 346 and 347 into engagement with the second contacts and their respective banks. By the movement of wiper 347 into engagement with its second bank contact, the circuit for stop relay 208 is opened, and by the movement of wiper 346 into engagement with its second bank contact, the first circuit for energizing start relay 209 is opened. If the second digit is registered on the second digit register by the time these operations following the registration of the first digit take place, the start relay 209 is again immediately energized from

ground by way of the resting contact and armature 317, off-normal springs 392', wiper 346 in engagement with the second bank contact. Relay 208, however, is slow to fall back, and retards its armatures attracted for an interval after its circuit is opened. 70

Returning now to the operation of the selector S', during the time in which relays 208 and 207 operate and stepping magnet 345 steps the wipers of the sequence switch S' into engagement with the second set of bank contacts, relay 106 of the selector S' is held operated over its local circuit including armature 115 and cam springs 124 and magnet 108 continues to step the switch wipers until the wipers 131, 133, and 135 are stepped into engagement with the first set of contacts of group 2. As soon as this position is reached, springs 124 again open thereby opening the local holding circuit of line relay 106. Since the stepping of the wipers over the last five contacts of group 1 takes place in a comparatively short time, relay 208 of the register sender has not had time to release its armatures. For this reason, the circuit of line relay 106 of the selector S' is now open whereupon relay 106 deenergizes and releases its armatures. Sometime after the release of the armatures of relay 106, stop relay 208 of the register sender releases its armatures, and again closes the control circuit, assuming that start relay 209 is again energized, but since release relay 107 is operated, no circuit is closed thereby, and impulsing relay 207 of the register sender remains deenergized. 85

The selector S' has now operated to position its wipers into engagement with the first set of contacts of the group corresponding to the first digit dialed, and is now about to select an idle trunk in that group. Line relay 106, in releasing armature 114, closes a circuit for switching relay 105 in series with stepping magnet 108 and closes the regular hunting circuit for stepping magnet 108, providing the trunk accessible at the first set of bank contacts in group 2 is busy at this time, which condition will be indicated by the presence of ground potential on the bank contact engaged by test wiper 133. Assuming this to be the case, the stepping magnet 108 again operates, this time over the circuit from ground on the contact engaged by test wiper 133, armature 110 and the resting contact, working contact and armature 119, resting contact and armature 114, interrupting springs 125, through the winding of stepping magnet 108 to battery, and continues to rotate the switch wipers until the wipers 131, 133, and 135 are rotated into engagement with the contacts terminating an idle trunk line, which will be assumed to be the trunk line comprising conductors 142, 145, and 144, the idle condition thereof being indicated by the absence of ground 110

potential on the release conductor 143 terminating in the contact now engaged by wipers 133. While the selector S' is hunting for an idle trunk, switching relay 105 is short circuited by reason of ground potential on both ends of its winding. As soon as this idle trunk is reached, however, the short circuit around switching relay 105 is removed and this relay operates over the circuit from ground potential on release conductor 23, through the winding of relay 105, working contact and armature 119, resting contact and armature 114, through the winding of magnet 108 to battery. Due to the high resistance of relay 105, current flow in this circuit is insufficient to cause the operation of stepping magnet 108, so the switch wipers are arrested in this position. Switching relay 105 operates, however, and applies ground potential to release conductor 143 by way of armature 110 and the working contact and wiper 133, and extends the connection by way of armatures 109 and 111 and their working contacts, wipers 131 and 135, trunk conductors 142 and 144 to the second selector S², wherein the connection extends to ground by way of armature 409 and the resting contact, and to battery by way of armature 411 and its resting contact, armature 418, through the winding of line relay 406.

As soon as the connection is so extended to second selector S², the circuit is completed for the line relay 406 in series with the impulsing relay 207 in the register sender providing the second digit of the called number has been registered on the second digit register and the start relay 209 has again operated. If the second digit has not yet been registered, the line relay 406 remains deenergized until it is registered and the start relay 209 of the register sender again energizes and closes the control circuit at its armature 229. Line relay 406 of the second selector S², in operating, performs circuit changes in the selector S² similar to those performed by the operation of the line relay 106 in the selector S', previously described. Selector S² then operates in a manner identical to the way in which selector S' operated, rotating its wipers over the bank contacts, short circuiting the impulsing relay 207 of the register sender by the closure of cam springs 424' each time the wipers are moved over the last five steps of contacts of a group. Each time the impulsing relay 207 is energized and deenergized, conductor 260 is grounded causing one of the two-step marking relays 351-355, inclusive, to operate and connect ground potential to the next marking conductor numbered higher in order; i. e., the first impulse to the marking relays (the first application of and removal of ground potential on conductor 260) operates relay 351; the second impulse operates relay 352 and releases relay 351; the third impulse operates relay 353 and releases relay 352; the fourth impulse operates relay 354 and releases relay 353; the fifth impulse operates relay 355 and releases relay 354; the sixth impulse reoperates relay 351, relay 355 remaining up; the seventh impulse reoperates relay 352, relay 351 and relay 355 remaining up. With relays 355 and 352 operated, ground potential is applied to marking conductor 337 by way of armature 365 and its working contact, armature 369 and its resting contact, armature 368 and its resting contact, and armature 367 and its working contact. As soon as conductor 337 is grounded, which results after the impulsing relay 407 has been energized and deenergized seven times, being deenergized for the seventh time as the wipers 432, 434 and 436 move over the last five contacts of group 6 (remembering that when wipers 131, 133, and 135 move off the last set of contacts of group 4, the wipers 132, 134, and 136 move on to the first set of contacts of group 5), a circuit is again closed for the stop relay 208, this time from ground by way of conductor 337, wiper 327 in engagement with its seventh bank contact, and wiper 347 in engagement with its second bank contact, through the winding of relay 208 to battery. Again relay 208 operates and opens the control circuit at armature 224, disconnects ground from the holding conductor 261 at armature 226 thereby allowing the operated marking relays to restore to normal, and closes a circuit for a stepping magnet 345 at armature 227. Stepping magnet 345, in operating, moves the wipers 347 and 346 into engagement with the third contacts in their respective bank, which opens the circuit of stop relay 208 and the present circuit of start relay 209.

When wipers 432, 434, and 436 move into engagement with the first set of bank contacts in group 7, the local circuit of line relay 406 including cam springs 424' is opened, and since the control circuit is now open also, stop relay 209 in the register sender having operated, line relay 406 falls back and closes the hunting circuit for magnet 408. The switch wipers are then further rotated until they are brought into engagement with the contacts terminating an idle trunk in group 7 which will be assumed to be the trunk comprising conductors 452, 453, and 454 terminating in connector C. When this trunk is reached, its idle condition being indicated by the absence of ground potential on the contact engaged by wiper 434, switching relay 405 operates and extends the control circuit by way of armature 409 and 411 and the working contact, wipers 432 and 436, conductors 452 and 454 to connector C, wherein the connection extends to ground by way of armature 461 and the resting contact and to battery by way of armature 464 and the resting contact, resting contact and armature 467, through the winding of line relay 457.

A short time after its circuit is opened, during which time the switch wipers moved to the first set of contacts in group 7 and line relay 406 fell back, relay 208 again releases its armatures and prepares the impulsing circuit at armature 224, and start relay 209 again operates after the third digit is registered from ground by way of resting contact and armature 318, closed off-normal springs 393', wiper 346 in engagement with its third bank contact, conductor 256, through the winding of relay 209 to battery, and closes the control circuit at armature 229. Again the impulsing relay 207 of the register sender 10 is operated this time in series with the line relay 457 of connector C. Relay 457, in operating, performs circuit changes similar to those performed by the operation of the line relays of the selectors S¹ and S²; namely, 15 the circuit of release relay 456 is closed at armature 470, armature 476 included in the initial energizing circuit of line relay 457 is shunted at armature 471, the circuit for sending impulses to (short circuiting) the impulsing relay in the register sender is prepared at armature 472, and the self-interrupting stepping circuit for magnet 460 is closed at armature 472. Relay 456 operates, closes a locking circuit for itself at 20 armature 466 to the grounded conductor 453, and performs other circuit changes to be described later. Magnet 460 operates in a buzzer-like manner to rotate the switch wipers in this case one complete revolution 25 until wipers 482, 484 and 486 are again rotated into engagement with the first, in this case dead, contact in group 0. By the rotation of the shaft carrying the wipers to this position, the cam springs 424 are closed ten 30 times by the action of the cam 421, thereby causing the impulsing relay 207 in the register sender to deenergize and reenergize ten times and ground the control conductor 260 ten successive times. The marking relays 35 351-355 are operated thereby, the first seven impulses are resulting in relay 355, relay 351 and relay 352 being operated as previously described, the eighth impulse reoperating relay 353 and releasing relay 352, the ninth impulse reoperating relay 354 and releasing relay 353, and the tenth impulse again reoperating relay 352. With relays 351, 352, 354, and 355 operated, ground potential is applied to marking conductor 340 from ground 40 by way of armature 365 and the working contact, armature 369 and the working contact, and armature 370 and the working contact. As soon as this conductor connected to contacts number 10 of the lower banks of the 45 digit registers is grounded, stop relay 208 is again energized, its energizing circuit this time including the now grounded conductor 340, wiper 328 in engagement with its tenth bank contact, and wiper 347 in engagement 50 with its third bank contact. Stop relay 208 again operates, opens the control circuit at armature 224, disconnects ground from conductor 261 at armature 226 thereby causing the release of the operated marking relays and closes the circuit of stepping magnet 345 at armature 227. Magnet 345 operates to step the wipers 346 and 347 into engagement with the fourth contacts in their respective banks, thereby opening the circuit of stop relay 208 and opening the present circuit of start relay 209. After the switch wipers have been rotated one complete revolution back to the first set of contacts in group 0, the local circuit of line relay 457 including springs 424 is opened, and since stop relay 208 55 has been operated to open the control circuit, line relay 457 is deenergized. By the release of armature 471, line relay 457 is disconnected from the control circuit, and by the engagement of armature 472 with its resting contact the control circuit is extended to include the winding of the control relay 459, working contact and armature 468, resting contact and armature 472, interrupting contacts 479, and the winding of stepping 60 magnet 460 connected to battery. 50

A short time after its circuit is opened stop relay 208 in the register sender releases its armatures and again prepares the control circuit at armature 224. After the fourth digit is registered, start relay 209 of the register sender again operates, this time from ground by way of resting contact and armature 319, closed off-normal springs 394, wiper 346 in engagement with its fourth bank contact, conductor 256, through the winding of relay 209 to battery, and again closes the control circuit at armature 229. Obviously, in this instance, as in previous instances, if the next digit is registered and relay 209 has already operated when stop relay releases its armature the control circuit will be closed immediately at that time. When the control circuit is again closed, impulsing relay 207 again energizes, this time in series with relay 459 and stepping magnet 460 of connector C. The current flow in this circuit is insufficient to operate stepping magnet 460. Relay 459, however, is energized through it is somewhat slow to pull up as well as slow to release, due to a slug on the armature end of its core (indicated in the drawing by the solid black portion on the upper end of its core). Relay 459, in operating, closes a circuit for slow-to-release relay 459', which operates and maintains its armatures attracted continuously even though its circuit is momentarily opened during operation of relay 459 as will be described presently. Relay 459, in operating, also closes a local circuit for stepping magnet 460 at armature 478, and at the same time short circuits itself and impulsing relay 207 in the register sender. The impulsing relay 207 in the register sender thereupon deenergizes and removes ground 65 from the control conductor 260 with the result 130

previously described. By reason of its slow acting characteristic, relay 459 does not de-energize immediately, therefore maintains the circuit of magnet 460 closed for a short time. This magnet therefore operates and 5 near the end of its stroke opens the control circuit at interrupting springs 479. After the elapse of the interval for which it is adjusted, relay 459 deenergizes and opens the circuit of stepping magnet 460 by releasing armature 478. Magnet 460 deenergizes and in so doing moves the switch wipers into engagement with the second set of bank contacts in group 0 in which access is had to the first 10 line in the group 0, and also closes the control circuit again by closing interrupting springs 479. Again impulsive relay 207 energizes to ground conductor 260, and after an interval relay 459 also energizes again. The above 15 described operations concerning relay 459 and stepping magnet 460 again take place, resulting in the movement of the switch wipers into engagement with the next set of contacts terminating the second line in group 0. 20 In a similar manner these operations are repeated until the impulsive relay 207 in the register sender has operated to ground conductor 260 eight successive times. As previously described, when eight impulses are 25 sent to the marking relays 351-355, inclusive, relays 351, 353, and 355 are operated with the result that ground potential is applied to marking conductor 338. When conductor 338 is grounded, a circuit is closed from ground 30 on this conductor, wiper 329 in engagement with its eighth bank contact (the fourth digit dialed having been eight), resting contact and armature 349, wiper 347 in engagement with its fourth contact, through the winding of 35 stop relay 208 to battery. Relay 208 then 40 operates with the usual results, including the closure of the circuit for magnet 345 for stepping the wipers 346 and 347 into engagement with the fifth contacts in their respective banks and the opening of the control circuit 45 thereby preventing further operation of the impulsive relay 207 of the register sender and the control relay 459 of the connector C. As a result wipers 481, 483 and 485 are brought 50 to rest on the contacts terminating line 8 of group 0 which is assumed to be the line comprising conductors 492 and 494 serving substations B¹-B¹⁰, inclusive.

The line serving substations B¹-B¹⁰, inclusive, may be either busy or idle at this time. If the line is idle, the proper signalling current is sent over the proper line conductor to signal the desired subscriber; but if the line is busy, the called subscriber 60 at substation A⁵ is notified accordingly. To describe these operations, it will first be assumed that the line serving substations B¹-B¹⁰, inclusive, is busy at this time, which will be indicated by the presence of ground 65 potential on the bank contact engaged by wiper 483. Since relay 459' is energized at the time when the wipers are rotated into engagement with the contacts terminating the desired line, a circuit is closed for busy relay 458 from ground by way of wiper 483, 70 armature 477 and the working contact, through the winding of relay 458 to battery. Relay 458 operates and connects conductor 480, connected to the busy tone machine BT (Fig. 1), to the upper talking conductor 75 452' at armature 474 at the same time disconnecting wiper 481 therefrom, prepares a holding circuit for itself at armature 475, and connects battery potential through the winding of magnet 460 to the lower talking 80 conductor 454' at armatures 476, at the same time disconnecting wiper 485 therefrom. Relay 459, in releasing its armatures following the opening of the control circuit by the stop relay 208 in the register sender, maintains the circuit for the slow acting relay 459' open. After an interval this relay deenergizes and completes the holding circuit for busy relay 458 in series with the lower winding 85 of switching relay 455, this circuit extending from ground on release conductor 453, through the lower winding of relay 455, armature 470, armature 475 and the working contact, spring 477' closed by the release of armature 477, through the winding of busy 90 relay 458 to battery. Busy relay 458 therefore remains energized, and switching relay 455 energizes, completing a holding circuit for itself to release conductor 453 at armature 463, connecting talking conductor 452 100 to talking conductor 452' now connected to the busy tone machine at armature 461, and connecting talking conductor 454 to talking conductor 454' now connected to battery through the winding of rotary magnet 460 105 at armature 462.

Certain operations now take place in the register sender and in the trunk relay group TRG as a result of the above described operations, which will now be considered. It 110 will be remembered that when stop relay 208 of register sender RS was operated the last time, a circuit was closed for the motor magnet of sequence switch S' which stepped the wipers 346 and 347 into engagement with the fifth contacts in their respective banks. By this operation, a circuit is immediately closed for ring control relay 210 in series with start relay 209, this circuit including conductor 259, wiper 346 in engagement with its fifth bank contact, and conductor 256. The operation of relay 209 at this time is without function. Relay 210 operates and disconnects relay 207 from the control circuit and connects conductor 96 to conductor 96' and conductor 97 to conductor 97'. It will also be recalled that the auxiliary test relay 204 is operated over a circuit completed at armature 225 each time stop relay 208 is operated. This relay, in operating, disconnects 120

conductor 97' and 96' from the ringing circuit and at the same time connects conductor 96' to test relay 203. This operation having had no function up to this time, now performs two functions, the first being to connect up the test relay 203 to test whether the connectors has engaged a busy or idle line, and the second being to delay the connection of the ringing current to the talking conductors until the switching relay 453 has had time to energize, providing the engaged line is idle.

In the present case, in which it has been assumed that the engaged line is busy, it will be remembered that both the busy relay 458 and switching relay 453 in the connector are operated, and that battery potential is connected to the lower talking conductor extending through the operated switches now connected by way of conductors 96 and 96' to the test relay 203. Relay 203 therefore operates, its circuit being completed through the winding of relay 204 to ground, and in turn completes a circuit which causes the disassociation of the register sender RS from the connection and the completion of a connection from the calling subscriber line to the talking conductors of the connector C, one of which is connected to busy tone machine. These operations take place as follows: The circuit closed by the energization of test relay 203 extends from ground through the resistance R, working contact and armature 216, conductor 94, wiper 84, armature 74, resting contact and armature 54, armature 40, armature 53, through the winding of switching relay 35, through the upper winding of switching relay 36 to battery. Due to the resistance R, the current flow of this circuit is insufficient to cause the operation of switching-through relay 36. Relay 35 operates, however, and performs the following circuit changes: At armature 55 a locking circuit is established for relay 35, and at armatures 53 and 54 the initial energizing circuit for this relay is opened. At armatures 51 and 58 the connection from the subscriber at substation A⁵ is switched through and extended to the talking conductors of the connector C, one of which is now connected to the busy tone machine, at the same time disconnecting conductors 96 and 97 of the register sender from the connection. At armature 56, the circuit of the switching relay 72 of the register sender selector RSS, and the circuit of the release relay 206 of the register sender is opened. Switching relay 72 releases its armatures, restoring the register sender selector RSS to normal condition, the wipers remaining in position on the previously selected contacts. Release relay 206 of the register sender also restores its armatures, disconnecting the interrupter I from the time impulse relay (to be later described) at armature 220, and closing the circuit for the release magnets

381-387, inclusive, at armature 222 and the resting contact. The magnets 381-387, inclusive, operate and restores their respective associated switch wipers to normal. By the return of wipers 346 to normal, the circuit of relays 210 and 209 is opened whereupon these relays restore to normal. The circuit of stop relay 208 was opened as soon as sequence switch S' moved its wipers into engagement with the fifth contacts following the final movement of the connector C. An interval thereafter, this relay restored its armatures to normal, opening the energizing circuit of auxiliary test relay 204 at armature 225. If this takes place before the register sender is disconnected from the connection by the operation of switching relay 35 of the trunk relay group TRG, relay 204 is held up in series with test relay 203 which is energized in series with the stepping magnet of the connector C, until it is disconnected therefrom by the operation of relay 35, after which relays 203 and 204 deenergize and restore to normal. The register sender is then in its normal condition and is again selectable to other register sender selectors.

The calling subscriber hears the busy tone from the busy tone machine BT and is thereby informed that the line served by the desired subscriber is busy at this time, whereupon he will replace his receiver with the intention of calling again at some later time. Replacing the receiver at the calling substation causes the release of the automatic switches and their restoration to normal in a manner to be described later.

In the above case, it was assumed that the line serving substations B¹-B¹⁰, inclusive, was busy when the wipers of the connector C were rotated into engagement with the bank contacts terminating this line. It will now be assumed that the called line is idle when the wipers of connector C are rotated into engagement with the contacts terminating the line. In this case, no ground potential is encountered by test wiper 484, and consequently test relay 458 is not operated. However, when relay 459 releases its armature 477, switching relay 455 is operated, this time over the circuit traceable from ground on release conductor 453, through its lower winding, armature 470, armature 475 and the resting contact, resting contact and armature 477, wiper 483, private normal conductor 493, through the winding of switching relay 495 of the lineswitch LS', through the winding of the stepping magnet 497 of this lineswitch to battery. Switching relay 495 operates in the well known manner to disconnect ground and battery through line relay 496 from the line conductors. Likewise switching relay 453 operates as in the previous case, closing a locking circuit for itself to release conductor 453 at armature 463, placing ground potential on the bank contact ter-

minating the private normal conductor 493, and on the corresponding bank contacts of other connectors multiply connected therewith, to mark the line to substations B¹-B¹⁰ 5 busy, by connecting the release conductor 453 to wiper 483 at armature 462 and the working contact, and by the actuation of armatures 461 and 464 the connection is extended to the called line by way of armatures 474 and 476 and their resting contacts, and wipers 481 and 485.

In the register sender RS, relay 204 again operates to disconnect the conductors 97' and 96' from the ringing circuit and connect conductor 96' to the test relay 203 as previously described when stop relay 208 operates to arrest the final movement of the switch wipers of the connector C. Start relay 209 and ring control relay 210 are again operated in series when the sequence switch wiper 346 20 is moved into engagement with its sixth bank contact, relay 210 operating to connect conductor 96 to conductor 96' and conductor 97 to conductor 97', all as described in the previous case. In this case, however, test relay 25 203 is not operated since the lower talking conductor extending forward and connected to conductor 96 is free from battery potential. Therefore the circuit for switching relay 35 30 is not closed at this time. Now when auxiliary test relay 204 releases its armatures which it does a short time after its circuit is opened by the release of stop relay 208, a circuit for signalling the desired subscriber is 35 prepared. This circuit is closed as soon as the final digit is registered—the registration of this digit, it will be recalled, consists in the setting of the wipers 342 and 343 in engagement with the contact set corresponding to the final digit dialed which was assumed 40 to be the digit 5—or if the final digit be already registered when relay 204 falls back, the circuit is closed at that time, and may be traced from conductor 80' to which the battery superimposed generator G⁵ and direct 45 battery is alternately connected by the action of the interrupter I⁵ (see Fig. 5), wiper 343 in engagement with its fifth bank contact, armature 307, conductor 251, through 50 the upper winding of ring cut-off relay 201, armature 211, armature 214 and the working contact (remembering that relay 202 is operated), armature 217, working contact and armature 230, conductor 97, wiper 87, armature 77, resting contact and armature 51, resting contact and armature 59, over the upper talking conductor extending through selector S¹, selector S², and connector C to line conductor 492, and thence through the ringers 55 at substations B¹-B⁵, inclusive, to ground. Only the ringer at substation B⁵ is tuned to respond to signalling current of the frequency of generator G⁵. This ringer therefore operates and continues to operate until the subscriber at substation B⁵ answers the call, or

until the call is abandoned by the calling subscriber. A small amount of ringing current also extends back to the receiver at the calling station through the condenser 52' to give the calling subscriber the usual ring back tone. 70 (Condenser 57' serves the same purpose when ringing current is sent over the lower talking conductor.)

When the subscriber at substation B⁵ removes his receiver to answer the call, a direct current bridge is placed across the line conductors 494 and 492 thereby closing a direct current circuit for the upper winding of ring cut-off relay 201 in the register sender RS. This circuit extends from conductor 80' to which the direct battery and battery superimposed generator is alternately connected by the action of the interrupter I⁵, through the upper winding of the ring cut-off relay 201 of the register sender RS, 80 over the upper talking conductor through the operated switches to the line conductor 492 as previously traced, and thence over the bridge at substation B⁵ to line conductor 494, back over the lower talking conductor 85 through the operated switches to conductor 251, and then by way of armature 62 and the resting contact, armature 58 and the resting contact, armature 76, wiper 86, conductor 96, armature 231 and the working contact, 90 armature 218 and the resting contact, working contact and armature 215 to ground. Ring cut-off relay 201 operates over this circuit and closes a locking circuit for itself at armature 213 to the grounded conductor 100 263, disconnects the ringing circuit at armature 211, and at armature 212 and the working contact completes a circuit for energizing the switching relay 35 by connecting ground through resistance R, to conductor 94, just as did test relay 203 in the previously described case. The switching relay 35 then operates and performs the circuit changes previously described which results in the restoration of the register sender and 105 the register sender selector RSS to normal, and the extension of the connection from the substation A⁵ through to the substation B⁵. In this case, back bridge relay 33 also operates as soon as switching relay 33 connects it in bridge of the called line by operation of the armature 54 and armatures 51 and 58, and in so doing completes a circuit for the completed-calls meter 18 by connecting direct ground to the meter conductor 24 at armature 47. Meter 18 now operates to register the call. It may be mentioned at this time that the magnet 18 was partially energized in series with resistance 110 45 when release relay 32 operated in its armature 44 at the initiation of the call. This current flow is insufficient to operate magnet 18, but is sufficient to maintain magnet 18 operated after it has been operated, thereby preventing the meter M from reoperat- 115 120 125 130

ing should the called subscriber open the circuit of the back bridge relay by inadvertently jiggling the switch-hook.

The two subscribers may now engage in conversation, talking battery being furnished to the calling line through the windings of the line relay 31, and to the called line through the windings of the back bridge relay 33. At the termination of the conversation both subscribers will replace their receivers on their respective switch-hooks. The replacement of the receiver by the called subscriber opens the bridge across the called line and causes the back-bridge relay 33 to deenergize and restore to normal. The replacement of the receiver at the calling substation opens the circuit of line relay 33. Relay 33 de-energizes and restores its armatures to normal, opening the circuit of the release relay 32 at armature 41. Shortly after its circuit is opened, release relay 32 deenergizes, disconnecting ground potential from the release conductor 23 and the serially related release conductors extending through the first selector S' , second selector S^2 , and connector C, and also from the private normal conductor 493 of the called line, at armature 42. By the release of armature 44, the locking circuit for switching relay 35, and the circuit for maintaining the magnet 18 of the meter M operated are opened. Magnet 18 deenergizes and restores to normal and switching relay 35 deenergizes and restores its armatures to normal. The removal of ground from release conductor 23 opens the circuit of switch relay 5. Relay 5 deenergizes and restores the lineswitch LS to normal, the wipers 14-17, inclusive remaining on the contacts last used.

The removal of ground potential from the release conductor 23 opens the holding circuit for switching relay 105 and release relay 107 of the first selector S' . Switching relay 105 thereupon deenergizes and restores its armatures to normal. Release relay 107 likewise deenergizes and restores its armatures to normal. By the engagement of armature 119 with its resting contact, the self-interrupting circuit for magnet 108 for returning the switch wipers 131-136, inclusive, to normal is closed, this circuit extending from ground by way of cam springs 123 closed by cam 120 whenever the switch is in an off-normal position, resting contact and armature 119, resting contact and armature 114, interrupting springs 125, through the winding of stepping magnet 108 to battery. Magnet 108 then operates in a buzzer-like manner until the switch wipers 131-136, inclusive, are restored to normal, in which position the stepping circuit is opened by the separation of cam springs 123. By the engagement of armature 116 and its resting contact, ground potential is re-applied to release conductor 23 by way of cam springs 122 also closed whenever the switch is in an

off-normal position, resting contact and armature 116 and contacts 110' closed by the release of armature 110 and is maintained thereon while the switch wipers are being rotated to normal, thereby protecting the trunk line, comprising conductors 22-25, inclusive, against seizure during this time. Cam springs 122 open as soon as the switch wipers are in their normal position, and the protecting ground potential is again removed from release conductor 23.

In a similar manner, second selector S^2 is restored to normal, relays 405 and 407 de-energizing when ground potential is removed from the release conductor 143. Likewise, the trunk line terminating in selector S^2 is guarded against seizure during the time the switch wipers are being rotated back to normal by the reapplication of ground potential to conductor 43 at springs 422'. Similarly, in the connector C, switching relay 455 and release relay 456 are restored to normal by the removal of ground potential from the release conductor 453, and the wipers of the connector C are rotated to normal by the operation of magnet 460, the self-interrupting circuit for this magnet being closed by the engagement of armature 468 and the resting contact, springs 423 now being closed. Also, the trunk terminating in connector C is guarded against seizure while the switch wipers are being rotated back to normal by the reapplication of ground potential to release conductor 453 from ground by way of cam springs 422 closed whenever the connector switch wipers are off-normal, armature 465 and its resting contact, and armature 462 and its resting contact.

The removal of ground from the private normal conductor 493 also deenergizes switching relay 495 of lineswitch LS' causing this relay to restore its armatures to normal, thereby placing lineswitch LS' in its normal position. All the switches and apparatus used in the establishment of the above connection have now been restored to normal and are in position ready to be taken for use in the extension of other calls.

It is evident from the foregoing description that a connection to any other subscriber on the same line is established in the same way, with the exception of the dialing of the last digit. To signal the subscriber at either of the substations B^1-B^4 , all operations are the same as in the previously described connections, except that a different generator is connected to the line conductor 492, the generator used being determined by the wiper setting of the frequency selecting switch of the register sender and which in turn is determined by the last digit dialled being either 1, 2, 3, or 4 in this case. To signal the subscriber at either of the substations B^6-B^{10} , the operations are likewise the same as in the previously described connection, except that

the final digit dialled in this case is either 6, 7, 8, 9, or 0 in which case the wiper corresponding to wiper 342 of the frequency selection switch of the regular sender used is moved past its first five contacts so that the circuit for the reversing relay corresponding to relay 202 of the register sender used is open. As a result, the generator used is connected to the line conductor 494 and the subscriber whose 10 ringer is tuned to respond to ringing current from the selected generator and is connected to that side of the line, is signalled.

Reverting call—Substation A⁶ to substation A²

15 In any telephone system giving service to party lines, provisions are made for making it possible for one subscriber to signal another subscriber on the same line, and this 20 preferably without apprising the other subscribers on that line. In this system described, the method in which reverting call switches (such as the reverting call switch RV shown in Fig. 5) are used is employed 25 for this purpose. According to this method, in order for a subscriber at one substation to be called to his telephone and for the calling subscriber to be suitably informed when a subscriber at the called substation removes 30 his receiver, the subscriber at the calling substation removes his receiver and dials a special reverting call number, which results in the connection through one or more selectors to a reverting call switch, and then dials an 35 other number which causes the reverting call switch to connect to certain of the generators G¹-G⁵, and the interrupter I⁵ so as to cause the ringing of the bells of the two substations alternately after the subscriber at the calling 40 substation has replaced his receiver. The ringing of the bells at the calling substation ceases as soon as the subscriber at the called substation removes his receiver. The subscriber at the calling substation then also removes 45 his receiver and commences conversation with the called subscriber.

The reverting call switch RV is of a new type in so far as its method of control is concerned, being in accordance with the general 50 object of its invention. Since the reverting call switch is connected to the calling line by way of one or more selector switches, and signalling current is projected back onto the calling line from the reverting call switch, 55 the connection must be extended from the calling line straight through to the reverting call switch independent of the ordinary bridges. In this system this is accomplished by a special switching through operation performed in the trunk relay group and controlled by means in the register sender used. The operation of the new reverting call switch and also the operation of the trunk relay group and the register sender when a connection is made with a reverting call switch

in so far as these operations differ from the operations performed in extending a call to a subscriber not on the same line with a calling subscriber will now be described. For this purpose it will be assumed that the subscriber at substation A⁶ wishes to have conversation with the subscriber at substation A². In this particular case with connections in the upper banks of the first and second digit registers of the register senders as shown 70 in Fig. 3, the special reverting call number is 21. To operate the ringer at substation A² and also the ringer at substation A⁶, generator G² must be connected to line conductor 3 and generator G¹ must be connected to line 80 conductor 2, and reverting call switch, to which the connection will be extended, must be operated so as to perform this operation. With the connections of the ringing generators G¹-G⁵, inclusive, and the interrupter 85 I⁵, to the bank contacts of the reverting call switches as shown in Fig. 5, the particular number in accordance with which the reverting call switch must be operated to alternately ring the bells of substation A⁶ and A² 90 is 38. Therefore, to call the subscriber at substation A², the subscriber at substation A⁶ removes the receiver and dials the number 2138.

Responsive to the removal of the receiver 95 at substation A⁶, the lineswitch LS operates to select and connect with a trunk extending to an idle first selector, which may be assumed to be the trunk comprising conductors 22-25, inclusive, terminating in the selector 100 S'. Responsive to the seizure of this trunk, register sender selector RSS operates to select and associate an idle register sender with this trunk, which again is assumed to be the register sender RS shown in Figs. 2 and 3. 105 Responsive to the dialing of the digit 2 by the calling subscriber, line relay 31 of the trunk relay group TRG operates to cause the registration of this digit on the first digit register, that is, the wipers 324 and 325 are 110 positioned in engagement with the second contacts in their respective banks. Likewise, the second digit 1 dialled by the calling subscriber is registered on the second digit register, that is, wipers 326 and 327 are positioned 115 in engagement with the first contacts in their respective banks; and the second and third digits 3 and 8 are respectively registered on the third and fourth digit registers, wiper 328 being positioned on its third bank contact, and wiper 329 being positioned on its 120 eighth bank contact. As shown in the drawing, wipers 324 and 326 are connected, ground potential is connected to the second contact of the banks of wiper 324 and relay 348 is 125 connected to the first and second contacts of the bank of wiper 326. Therefore as soon as the first digit 2 and second digit 1 have been registered, a circuit is closed for shunt relay 328. This relay operates and removes the 130

short circuit from the lower winding of switching-through control relay 303. The function of this operation will become obvious from later descriptions.

5 After the registering of the first digit 2, first selector S' operates to rotate wipers into engagement with the first set of contacts of group 2 corresponding to the wiper setting of the first digit register of the register sender, and then further rotates them to select and extend the control circuit to an idle second selector, which again may be assumed to be the selector S^2 shown in Fig. 4. Likewise as soon as the second digit is registered 10 the second selector S^2 rotates its wipers into engagement with the first set of contacts of group 1 corresponding to the wiper setting of the second digit register, and then further rotates them to select and extend the control circuit to an idle reverting call switch accessible in that group of contacts, which may be assumed to be the reverting call switch shown in Fig. 5 accessible by way of the trunk comprising conductors 442-444, inclusive.

15 25 The operation of the reverting call switch RV as regards the positioning of the switch wipers 562-569, inclusive, in engagement with proper set of contacts in the proper group is the same as the operation of the connector C , 30 being controlled by the setting of the wipers of the third and fourth digit registers in the register sender as described above. Line relay 505, release relay 506, and slow acting relay 507 correspond to, have the same function 35 as, line relay 457, release relay 456, and slow-acting relay 459 of the connector C , and operate in the same way. After the third digit has been registered and the control circuit has 40 been extended to the reverting call switch, line relay 505 operates (in series with the impulsive relay 207 of the register sender) and closes the circuit for the release relay 506 at armature 544, shunts armature 550 at armature 545, prepares a circuit for shunting relay 207 of the register sender at armature 546, and at armature 547 closes the self-interrupting circuit for stepping magnet 515. Release relay 506 operates and locks to the release conductor 443. Magnet 513 operates until 45 the switch wipers 62, 64, 66, and 68 are rotated into engagement with the first set of contacts in the group corresponding to the setting of the third digit register wiper which in this case is group 3. After this selection has 50 taken place, line relay 505 deenergizes thereby disconnecting itself from the control circuit and including slow-acting relay 507 and rotary magnet 513 in series in the control circuit, whereupon the relays 507 and magnet 513 operate alternately until the switch wipers 55 have been positioned in engagement with the set of bank contacts of the selected group corresponding to the setting of the fourth digit register wiper, which in this case has 60 been assumed to be represented in the draw- 65

ing by bank contacts 572-575, inclusive. Furthermore, each time control relay 507 operates, it also closes a circuit for auxiliary release relay 508. Relay 508 is energized, and being slow acting, maintains its armature attracted during the intermittent operation of relay 507. Relay 508, in operating, closes a circuit for the lower winding of two-step relay 504. Relay 504 operates in its first step, operating only armature 540, thereby preparing a circuit for operating to its second step. In operating relay 508 also prepares a circuit, to be described later, at armature 556, and closes a circuit for release relay 509 at armature 555. Release relay 509 operates and connects another source of ground potential to release conductor 443 at armature 557.

70 As previously described, as the wipers are moved into engagement with the proper set of bank contacts, the stop relay 208 in the register sender RS operates to open the control circuit, but in this particular case, since the short circuit around the lower winding of relay 303 has been removed by the operation of armature 394, relay 303 operates in series 75 with stop relay 208 and closes a locking circuit for itself at armature 309 to the grounded conductor 263, prepares a circuit for controlling the switching through operation in the trunk relay group TRG (to be described 80 presently) at armature 308, and at armature 309' closes a circuit for the delay relay 388 which may be traced from ground by way of armature 537 and the resting contact of the reverting call switch RV to the upper heavy 85 control conductor extending through the second selector S^2 and first selector S' to conductor 22', and thence by way of armature 59 and the resting contact, armature 51 and the resting contact, armature 77, wiper 87, 90 conductor 97, conductor 262, through the winding of relay 388, armature 309' and the working contact to battery. Relay 388 operates over this circuit and disconnects ground 95 from conductor 252 at armature 254. It is 100 noted that the time that conductor 252 is grounded before relay 388 operates is too short to cause the switching-through operation (to be described presently) to take place.

105 After the switch wipers have been positioned on their proper contacts and the stop relay 208 of the register sender has operated and opened the control circuit, relay 507 falls back and maintains the circuit of slow-acting relay 508 open at armature 552. A short 110 time after its circuit is opened, relay 508 releases its armatures, and in so doing removes the short circuit from the upper winding of relay 504 at armature 554. Relay 504, now 115 being energized from ground on release conductor 443, working contact and armature 540, through its upper and lower windings in series to battery, operates in its second step, operating all of its armatures with the following results: At armature 451 a circuit to 120 125 130

65 been assumed to be represented in the draw-

be described later is prepared. At armature 538 a circuit is closed which may be traced from conductor 581 to which ground potential is intermittently connected by the inter-
 5 rupter I^5 , bank contact 572, wiper 562, armature 538, through the winding of relay 503 to battery. Likewise at armature 542 an intermittently interrupted circuit is closed for relay 512, this circuit extending from conductor 581 and including bank contacts 575 and the wiper 568. The function of the intermittent operation of relays 512 and 503 will
 10 be described presently. By the engagement of armatures 537 and 543 with their working contacts, the upper and lower windings of relay 501 are bridged across the heavy control conductors. Furthermore by the disengagement of armature 537 from its resting contact, ground potential is removed from the
 15 20 upper heavy control conductor 442.

By the removal of ground potential from the conductor 442, the circuit of relay 388 in the register sender is opened, causing this relay to deenergize and initiate the switching-
 25 through operation in the trunk relay group TRG, this operation having been delayed until now to allow time for the bridging of relay 501 across the control conductors in the reverting call switch. By the release of
 30 armature 389 of relay 388, direct ground potential is connected to conductor 252 via armature 308 and its working contact which conductor is connected by way of resting contact and armature 212 to conductor 94. A
 35 circuit is thus completed for switching relay 35 and switching-through relay 36 of the trunk relay group TRG in series as previously traced. In this case, however, since direct ground is connected to conductor 94 rather than grounded through resistance R as in the
 40 previous case, both relays 35 and 36 are operated. Relay 35, in operating, again closes a locking circuit for itself to the conductor grounded at armature 44, opens the holding circuit for switching relay 72 of the register sender RSS at armature 56, and also opens the circuit of release relay 206 of the register sender RS. Relay 72 deenergizes and thus places the register sender selector RSS in normal position, the wipers remaining on the contacts last selected. Opening the circuit of release relay 206 to the register sender RSS results in the restoration of the register sender to normal as previously described. Relay 36, in operating, closes a locking circuit for itself at armature 60 to the grounded release conductor 23 and connects the trunk conductors 22 and 25 directly to conductors 22' and 25' at armatures 59 and 62. By the
 55 separation of contacts 59' and 62' under the control of armatures 59 and 62, respectively, line relay 31 is disconnected from in bridge of the trunk conductors. This relay then deenergizes and opens the circuit of release relay 32. Relay 32 likewise deenergizes and

restores its armatures to normal, and in so doing disconnects ground from the release conductor 23 at armature 42. Ground potential is still maintained on release conductor 23, however, since this release conductor and the release conductors of selector S^1 and selector S^2 are serially connected to release conductor 443 to which ground potential is connected by way of armature 557. At armature 44 the holding circuit of relay 35 is opened whereupon this relay deenergizes and
 70 75 restores its armatures to normal.

When relay 36 operates and extends the connection straight through to the reverting call switch RV, a direct current circuit is closed for relay 501 which includes the two line conductors 2 and 3 and the bridge at the calling substation in series, bearing in mind that all the above described operations following the dialing of the last digit take place in a comparatively short time before the calling subscriber has had time to replace his receiver. Relay 501 operates and closes another circuit for slow-acting relay 508 which includes armature 531 and the resting contact, and resting contact and armature 553. Relay 508 again operates and at armature 555 again establishes the circuit slow-acting release relay 509. Again it should be noted that the operations described above resulting from the release of relay 508 and the energization of relay 504 in its second step all take place in a comparatively short time so that relay 501 operates to reestablish a circuit for relay 508 which in turn reestablishes the circuit of relay 509 before relay 509 has had time to release its armatures. Therefore ground potential is maintained on the release conductor 443 continuously to maintain the connection intact.

After completing the dialing of the four digits, the calling subscriber at substation A⁶ replaces his receiver. Replacing the receiver at substation A⁶ opens the bridge across the line conductors 2 and 3, thereby interrupting the circuit of battery feed relay 501. This relay then deenergizes and in so doing closes a circuit which may be traced from ground by way of armature 531 and the resting contact, working contact and armature 541, armature 556 and the working contact, resting contact and armature 559, through the winding of ring control relay 502. The relay 502 operates and at armature 533 and the working contact reestablishes a holding circuit for relay 508 to maintain this relay operated, since the holding circuit thereof, including armature 531 and its working contact, is opened by the release of armature 531. At armatures 532 and 534, the circuits are prepared for signalling the two subscribers alternately which will be described presently.

It will be recalled that when relay 504 operated, circuits were closed for relays 503 and 512 from the common conductor 81 con- 130

neeted to wiper 82 of interrupter I⁵, causing these relays to operate intermittently. The wiper 583 of the interrupter I⁵ is secured to the same shaft as the wiper 582, and closes the circuit for relay 584 for a certain length of time when no ground potential is applied to conductor 581, and again for a certain length of time during the time when ground potential is applied to conductor 581. Thus relay 584 connects the battery superimposed generator to the common ringing conductors 576, 577, etc. for an interval during the time when relays 503 and 512 are operated, and again for an interval during the time when relays 503 and 504 are not operated. Now, when relays 503 and 512 are operated and relay 584 is also operated, a circuit may be traced from the battery superimposed generator G¹, working contact and armature 526, common ringing conductor 576, bank contact 526, common ringing conductor 576, bank contact 574, wiper 566, working contact and armature 561, through the winding of cut-off-control relay 511, working contact and armature 536, working contact and armature 534, working contact and armature 543 to the lower heavy control conductor extending through the selector S², and selector S¹, trunk relay group TRG, lineswitch LS to line conductor 2, through the ringer at substation A⁶ to ground. During the time that relay 584 is operated and relays 503 and 512 are not operated, a circuit may be traced from battery superimposed generator G², working contact and armature 527, ringing conductor 577, bank contacts 573, wiper 564, resting contact and armature 561, through the winding of the cut-off-control relay 511, resting contact and armature 535, working contact and armature 532, working contact and armature 537 to the upper heavy control conductor extending through the selector S², selector S¹, trunk relay group TRG, lineswitch LS to line conductor 3, through the ringer at substation A² to ground. It is understood, of course, that ringing current also flows through the other ringers to ground and at the other substations, but that the other ringers in each case are tuned so as not to respond to the frequency of ringing current supplied to the line conductors. The ringers at substation A² and A⁶ will now ring alternately until the subscriber at substation A² removes his receiver to answer the call (or until the subscriber at substation A⁶ momentarily removes his receiver to abandon the call as will be mentioned later).

When the subscriber at substation A⁶ removes his receiver to answer the call, a direct current bridge is placed across line conductors 2 and 3 which closes a direct current circuit for the cut-off-control relay, this circuit including the two line conductors and the bridge at the substation A⁶ in series traceable from direct battery or battery superim-

posed generator applied to either conductor 76 or 77 over either one or the other of the ringing circuits traced, depending on the particular time when the receiver at substation A² is removed, back over the other ringing circuit to ground by way of armature 538 and the working contact, or armature 536 and the resting contact as the case may be. Relay 511 operates immediately and closes the circuit for ring-cut-off relay 510 at armature 560. Relay 510 operates and closes a locking circuit for itself at armature 558 and opens the circuit of the ring control relay 502 at armature 559. Relay 502 then deenergizes and opens further the ringing circuit by permitting armatures 532 and 534 to disengage their working contacts and at the same time again bridges battery feed relay 501 across the line conductors by permitting these armatures to engage their resting contacts. By permitting armature 533 to disengage its resting contact, the present holding circuit for release relay 508 is opened. Battery feed relay 501 operates again as soon as it is bridged across the line conductors and again establishes a holding circuit for release relay 508 which includes armature 531 and the working contact, and resting contact and armature 533.

The cessation of the ringing of the bells at the substation A⁶ indicates to the subscriber thereat that the subscriber at substation A² has removed his receiver, whereupon the subscriber at substation A⁶ also removes his receiver and commences conversation. The two subscribers may then engage in conversation, talking battery being furnished through the windings of the battery feed relay 501.

At the termination of the conversation both subscribers will replace their receivers, thereby opening the bridge across the line conductors. This interrupts the circuit of the battery feed relay 501 which thereupon deenergizes and opens the circuit of relay 508. Shortly after its circuit is opened, relay 508 deenergizes and opens the circuit of release relay 509 at armature 555. Relay 509 releases its armature shortly thereafter and thereby removes ground potential from the release conductor 443. The removal of ground potential from the release conductor 443 opens the holding circuits of relays 504, 506, and 510. Relays 504, 506, and 510 thereupon deenergize and restore their armatures to normal. Relay 506 in restoring its armature 551 to normal, closes the self-interrupting return-to-normal circuit of stepping magnet 513, this circuit including cam springs 523 closed by cam 520 whenever the switch wipers are in an off-normal position, armature 551 and its resting contact, and armature 547 and its resting contact, and interrupting contacts 525 of magnet 513. Magnet 513 therefore operates in a buzzer-like manner to rotate the switch wipers 562-569 to their normal position. During this time ground potential is 130

reapplied to release conductor 443 by way of cam springs 522, armature 548 and its resting contact, closed contacts 540', thereby guarding the reverting call switch RV against seizure while the switch wipers are being rotated to normal.

The removal of ground from release conductor 443 also opens the holding circuits for the switching relay and the release relay in selector S' and in selector S², for relay 36 in the trunk relay group TRG, and for switching relay 5 in the lineswitch LS. The release of the switching relay and the release relay in selector S² and in selector S' causes these selectors to rotate their wipers to their normal position as previously described. Switching relay 36, in deenergizing, restores its armatures thus restoring the trunk relay group TRG to normal; and switching relay 5 likewise, in deenergizing, releases its armatures, thereby restoring the lineswitch LS to its normal condition, the wipers 14-17, inclusive, remaining on the contacts last used. All the apparatus has now been restored to normal and is ready to be taken into use in the establishment of other connections.

Had the subscriber at substation A² not answered the call, the subscriber at substation A⁶ would have stopped the signalling and initiated the release of the operated switches by momentarily removing his receiver. Obviously, removing the receiver at substation A⁶ would cause the same operations in the reverting call switch RV as those initiated by the removal of the receiver in substation A², and the replacement of the receiver again would initiate the release of the operated switches as described above.

40 Call to operator—short number call

In the establishment of the above connection to a reverting call switch, it was shown how the switching-through relay 36 in the trunk relay group TRG caused the connection to be extended straight through independent of all bridges to the reverting call switch, this operation being controlled by means in the register sender. For well known reasons it is also desirable at times that when a connection is established to an operator, the connection be clear of all bridges up to the operator's position. It is also common telephone practice to assign a number for calling the operator comprising a relatively few number of digits. In the following description it will be shown how the switching relay 36 in the trunk relay group TRG is operated to switch the connection straight through to an operator's position, this operation controlled by means in the register sender in response to the dialing of the operator's call number. To describe these operations, it will be assumed that the subscriber at substation A⁵ wishes to call the operator. To initiate the call,

the calling subscriber removes his receiver and dials the call number of the operator which in this case, with the connections in the upper banks of the first and second digit registers of the register senders as shown in Fig. 3, is 22.

Responsive to the removal of the receiver at the substation A⁵, a bridge is placed across the line conductors 2 and 3 which initiates the operation of the lineswitch LS to select and extend the connection to an idle trunk line, which again may be assumed to be the trunk line comprising conductors 22-25, inclusive, terminating in the selector S'. When this trunk line is seized the register sender selector RSS associated with this trunk line is caused to operate and select an idle register sender which again may be assumed to be the register sender shown in Figs. 2 and 3, accessible by way of conductors 94-97, inclusive.

Responsive to the dialing of the first digit 2 line relay 31 in the trunk relay group TRG operates and causes the digit 2 to be registered on the first digit register in the register sender RS, which consists in the setting of wipers 324 and 325 in engagement with the second contacts in their respective banks. Responsive to the dialing of the second digit 2, line relay 31 again operates and causes the registration of this digit on the second digit register, which consists in the setting of the wipers 326 and 327 into engagement with the second contacts in their respective banks. As soon as the second digit is registered, a circuit is again closed for shunting relay 348 which may be traced from ground by way of the second contact engaged by wipers 324, wiper 326 in engagement with its second bank contact, through the winding of relay 348 to battery. Relay 348 operates and opens the short circuit around the lower winding of relay 303 by armature 349.

As soon as the first digit is registered, start relay 209 of the register sender is operated as previously described, the energizing circuit including armature 316 and its resting contact and wiper 346 in engagement with its first bank contact, and closes the bridge across conductors 22' and 25' at armature 229 thereby closing the control circuit and initiating the operation of the selector S'. Selector S' rotates its wipers into engagement with the first set of contacts in group 2 corresponding to the wiper setting of the first digit register, and then further rotates them to select an idle trunk in group 2, which again may be assumed to be the trunk comprising conductors 141-144, inclusive, terminating in selector S². The stop relay 208 functions as previously described, operating as the selector wipers are being moved over the last five contacts of group 1, and causes the movement of the sequence switch wipers 346 and 347 into engage- 130

ment with the second contacts in their respective banks.

As soon as the second digit is registered, the second selector S^2 likewise operates and rotates its switch wipers into engagement with the first set of bank contacts in group 2 corresponding to the wiper setting of the second digit register, in which group it is assumed the trunks to the operator are accessible, and then further rotates its wipers to select an idle trunk accessible in this group. Again stop relay 208 is operated while the wipers of selector S^2 are rotating over the last five contacts of group 1 when ground potential is connected to conductor 332 as previously described, in this case, however, in series with the lower winding of relay 303, the circuit extending from grounded conductor 332, through the lower winding of relay 303, wiper 327 in engagement with its second bank contact, wiper 347 in engagement with its second bank contact, through the winding of relay 208 to battery. Therefore relay 303 also operates and in so doing closes a locking circuit for itself at armature 309 and closes the circuit for operating the switching-through relay 36 in the trunk relay group TRG at armature 308. This circuit is closed only for an instant at this time, however, because relay 388 is operated over a circuit closed by the operation of magnet 309' and disengages armature 389 from its resting contact. As a result, relay 36 is not operated at this time. The circuit over which relay 388 is operated extends from ground by way of the resting contact and armature 409 of the second selector S^2 (remembering that this is taking place while the wipers of selector S^2 are rotating over the last five contacts of group 1) over the upper heavy conductor extending through selector S' to conductor 22', and thence by way of armatures 59, 51, 77, wiper 87, conductor 252, through the winding of relay 388, armature 309' to battery.

After selecting the proper group, the selector S^2 continues to rotate until it finds an idle trunk which may be assumed to be the trunk comprising conductors 437, 438, and 439 terminating at the operator's position in the jack J. When this trunk line is selected, the switching relay 405 of the selector S^2 operates as previously described to extend the connection to the seized trunk line. In so doing direct ground is disconnected from the upper talking conductor by the disengagement of armature 409 from its resting contact, and ground through resistance R^5 by way of resting contact and armature 594 is substituted therefor. Due to this resistance R^5 , the current flow now through relay 388 is insufficient to maintain this relay operated. Relay 388 therefore deenergizes and by releasing armature 389 places direct ground potential on conductor 252, which causes the

energization of switching relay 35 and switching-through relay 36 in the trunk relay group TRG over the previously traced circuit. Relay 35 operates and causes the release and restoration of the register sender RS to normal and the restoration of the register sender selector RSS to normal condition, as previously described. Relay 36, in operating, closes a locking circuit for itself to the release conductor 23 at armature 60, and at armature 59 and 62 extends the connection straight through to the operator's position. A direct current circuit is thus completed for the line relay 592 at the operator's position, this circuit extending from ground by way of resistance R^5 and the resting contact, and armature 594 to the upper heavy talking conductor connected to line conductor 3, over the bridge at the calling substation A^5 to line conductor 2, over the lower heavy talking conductor to armature 597 and the resting contact, through the winding of relay 592 to battery. Relay 592 operates over this circuit and closes the circuit for lighting the lamp L at armature 598, and closes the circuit for release relay 590 at armature 599. Release relay 590 operates and connects ground potential to release conductor 438 to hold up the operated switches, this taking place before the release relay 32 in the trunk relay group TRG has had time to release its armatures (the circuit of relay 32 having been opened by the release of line relay 31 which was disconnected from in bridge of the calling line conductors by the operation of switching-through relay 36).

In response to the lighting of the lamp L, the operator inserts the plug of her cord into jack J. The cord (not shown) may be of any suitable type having battery potential connected to the sleeve conductor. Inserting the plug into jack J closes the circuit for sleeve relay 591 which operates and disconnects ground through resistance R^5 and relay 592 from the talking conductors by disengaging armatures 594 and 597 from their resting contacts, and extends the connection to the cord circuit by causing these armatures to engage their working contacts. At armature 595, the circuit of lamp L is opened, and at armature 596 a holding circuit is closed for release relay 590 to maintain this relay operated, its initial energizing circuit being opened by the restoration of armature 599. After throwing the listening key in the cord circuit, the operator and the calling subscriber may engage in conversation.

At the termination of the conversation, the subscriber at substation A^5 will replace his receiver and the operator will remove her plug from the jack J. Removing the plug from jack J opens the circuit of relay 591. This relay, in deenergizing, opens the circuit of release relay 590. Shortly thereafter

relay 590 releases its armature 593 thereby removing ground from the release conductor 438 which initiates the release of the operated switches as previously described.

5 *All trunks busy operation*

In every case, in the above descriptions of the establishment of connections, it was assumed that the selectors in performing their 10 trunk selecting operation, always found an idle trunk over which to extend the connection to a succeeding switch. Under heavy traffic conditions, however, there is a possibility of all the trunks accessible in a selected 15 group of bank contacts being busy at the particular time that the selecting operation is performed. When such a condition is encountered, the calling subscriber must be suitably informed that the desired connection 20 is not being extended, so that he will hang up his receiver and try to complete the call a little later. The operation of the new 25 selectors as introduced by this invention and the way in which the calling subscriber is signalled when a selector encounters an all- 30 trunks-busy condition in a certain selected group will now be described.

It will be assumed that the calling subscriber at substation A⁵, for example, is attempting 35 to extend a connection to some other subscriber, and has removed his receiver and is dialling the directory number of the desired subscriber. It will further be assumed that the lineswitch LS, responsive to the removal 40 of the receiver at the substation A⁵, operated to extend the connection to the trunk, comprising conductors 22-25, inclusive; that responsive to the seizure of this trunk, the register sender selector RSS operated 45 to associate the register sender RS shown in Figs. 2 and 3 with the seized trunk line; that the first selector S' has been operated to select the proper group of contacts, corresponding to the wiper setting of the first 50 digit register, for example, group 3; and that the selector is now engaging in its trunk hunting movement. The wipers 131, 133, and 135 are thus rotated over the contacts of this selected group under the action of the stepping 55 magnet 108, the circuit thereof being successively closed from ground potential present on all the test contacts representing busy trunks engaged by test wiper 133.

It will be recalled that the stop relay 208 60 is operated when the selector wipers are rotating over the last five contacts preceding the proper group of contacts, and, in operating, closes the circuit for stepping magnet 345 which steps the sequence switch wipers 346 and 347 into engagement with the next set of bank contacts, in this case, the second set, and that as soon as the second digit is registered, the start relay 209 is energized, thus 65 conditioning the register sender for controlling the operation of a selected second selec-

tor. In the present case, however, it is assumed that all the trunk lines accessible in group 3 are busy. Therefore the switch wipers continue to rotate until they come into engagement with the eleventh set of bank contacts, represented in the drawing as bank contacts 152, 153, and 154. Bank contact 152 is multiply connected with the corresponding bank contacts of the eleventh set of all the groups. The bank contact 153 and the corresponding bank contacts of the eleventh set of all the groups is unequipped. Bank contacts 154 is multiply connected with the corresponding bank contacts of the eleventh set of all the groups to conductor 141 to which battery potential is intermittently connected by the action of the interrupter I'. Since there is no ground potential present on bank contact 153, no circuit is closed for magnet 108 when the wipers are moved into engagement with the contact sets comprising contacts 152, 153 and 154, and consequently the wipers come to rest in this position.

It will be recalled that in the establishment of the connection to substation B⁵, as previously described, when wiper 133 engages the then ungrounded contact 143, the short circuit was moved around switching relay 105 causing the operation of this relay, which in operating extended the connection to the selector S². The extension of the connection again closed the circuit for the impulsing relay 207 in the register sender in series with relay 406 in selector S² whereupon the selector S² was operated, the impulsing relay 207 in the register sender being short circuited intermittently by the action of the cam 421'. In the present case, with wipers 131, 133, and 135 in engagement with contacts 152, 153, and 154, respectively, the short circuit is likewise removed from the switching relay 105, causing this relay to energize. Again a circuit is established for impulsing relay 207 from ground potential supplied to conductor 140 at the busy tone machine BT, bank contact 152, wiper 131, and then through the winding of impulsing relay 207 to wiper 135 as traced in the previous descriptions, to conductor 141 to which battery potential is intermittently applied. Again the impulsing relay 207 is energized and deenergized intermittently and the register sender operates just as though the connection had been extended to a second selector. Furthermore, the register sender continues to operate just as though the connection is being extended to the called line. The sequence switch wipers 346 and 347 are moved successively over their bank contacts under the control of the stop relay 208, and when wiper 346 engages its fifth bank contact, a circuit is closed for start relay 209 and ring control relay 210 in series, relay 210 functioning to connect conductors 96 and 97 to conductors 96' and 97', respectively. It will also be remembered that relay 130

204 is operated each time stop relay 208 operates. Therefore conductor 96' is connected to the test relay 203 at the time control relay 210 operates. It will further be recalled that when a connector is operated to connect with the busy subscriber's line, battery potential through the stepping magnet of the connector is connected to the lower talking conductor which causes the operation of test relay 203. In this case test relay 203 likewise operates, battery potential being intermittently connected to the lower talking conductor by way of interrupter I'. Test relay 203, in operating, again connects ground potential through resistance R' by way of working contact and armature 216 to conductor 94, which causes the operation of switching relay 35 as previously described. Relay 35 performs its usual operations, and in so doing, connects the upper incoming line conductor to talking conductor 221 to which the busy tone machine BT is now connected. The calling subscriber now hears the busy tone, indicating to him that the connection has not been completed, whereupon he will replace his receiver and try again at some later time.

It will be noted that the connection to the eleventh set of bank contacts of all the groups of selector S² are the same as those of selector S'. It is evident, therefore that should the selector S² encounter an all-trunks-busy condition in a selected group, the same operations described above would take place, and the calling subscriber would be given the busy tone in the same way.

Alarm signal operations

In this system means have been provided for releasing a register sender taken into use and giving the attendant at the exchange an alarm whenever a register sender is held for use for a longer period of time than is ordinarily required for completing a connection and calling the called subscriber to his telephone. This condition occurs whenever a subscriber's line becomes short circuited, or the battery side of a line becomes grounded, or whenever the receiver at some substation is removed and is not replaced before the elapse of the predetermined period. Obviously, the attendant at the exchange should be notified of such conditions.

The manner in which this is accomplished in the present system will now be described. For this purpose it will be assumed that the subscriber at substation A, for example, has removed his receiver, and after partially dialing the number of some subscriber that he intended to call, stops dialing for some reason or other, abandons the call, and neglects to replace his receiver on the switchhook. Again, responsive to the removal of the receiver at the substation A⁵, the line-switch LS operates and seizes an idle trunk

which may be assumed to be the trunk comprising conductors 21-25, inclusive, and responsive to this seizure, the register sender selector likewise operates to select an idle register sender which may be assumed to be the one shown in Figs. 2 and 3. As will be recalled from a previous description, release relay 206 is operated when the register sender is seized in series with the lower winding of alarm relay 34 of the trunk relay group TRG, relay 34 being insufficiently energized to cause its operation at this time. Relay 203 is operating, as described previously, places ground potential on holding conductor 261 at armature 222 and the working contact by way of armature 226 and the resting contact, and at armature 220 connects the interrupter I² to the conductor 200' extending to the time impulse relays 240 and 241. The interrupter I² places ground potential on conductor 200 periodically, the length of time between successive applications being somewhat longer than is ordinarily required to complete a connection and call the desired subscriber to his telephone. Upon the first application of ground potential to conductor 200 now connected to conductor 200', two-step relay 240 operates in its first step and prepares a circuit at armature 243 for energizing this relay in its second step, armature 242 remaining in engagement with its resting contact thereby short circuiting the lower winding of relay 240. As soon as ground potential is removed from conductor 200', the short circuit is removed from the lower winding of relay 240, which thereupon operates in its second step and extends the impulse conductor 200' to the second two-step relay 241. As stated, ground potential is not applied to conductor 200' again until after the elapse of a predetermined interval during which the entire connection should be set up and the called subscriber summoned to his telephone. If such is the case, relay 206 releases when the called man answers, disconnects conductor 200 from conductor 200' by releasing armature 220, and also releases the two-step relay 240 by removing ground potential from conductor 261 by the release of armature 222, and the register sender is released in the ordinary way as previously described.

In the present case, however, since it has been assumed that the subscriber at substation A abandons the call before completion and neglects to replace his receiver on the switchhook, the register sender will still be engaged after the elapse of the aforesaid interval. Therefore, when ground potential is again applied to conductor 200 in this case still connected to conductor 200', relay 241 operates in its first step and prepares the circuit for operating to its second step at armature 245 and the working contact, and when ground is removed from conductor 200' the second time, this relay operates to its second

step and closes a circuit for guard release relay 205 at armature 244. Relay 205 then energizes and connects resistance R' by way of the working contact and armature 219 in multiple with relay 206. The flow of current in the lower winding of alarm relay 34 in the trunk relay group TRR is sufficiently increased thereby to cause this relay to operate. In operating, relay 34 closes a locking circuit for itself to release conductor 23 and armature 29 and opens the circuit of switching relay 72 and release relay 206 by disengaging armature 50 from its resting contact. As a result, the switching relay 72 de-energizes and thereby restores the register sender selector RSS to its normal condition, the wipers remaining on the contacts last used, and by the deenergization of release relay 206, the register sender is released and restored to normal as previously described. As a further result of the operation of relay 34, ground potential is placed on the alarm conductor 99 at armature 48 thereby causing the lighting of the lamp L' and the sounding of an alarm (not shown) to signal the attendant at the exchange; and at armature 48' conductor 98 connected to a tone machine (not shown) is connected to the upper talking conductor. The attendant traces the call by means of the lamp L' and then determines the nature of the trouble and in this case takes the necessary steps to notify the subscriber at substation A⁵ that his receiver is off the switch-hook.

If the subscriber at substation A⁵ merely paused unduly, and attempts to continue dialling before the attendant has notified him, he will hear the distinctive tone, which will indicate to him that he must hang up his receiver and dial the complete number over again in order to obtain the desired connection.

It is obvious, of course, that a short circuit across the line conductors 2 and 3 would also result in the above operations and the signalling of the attendant, who, after determining the line upon which trouble exists, would take the necessary steps to have it corrected.

It should also be mentioned that should a selector or a connector fail to operate correctly in that it did not short circuit the impulsive relay in the register sender, due to dirty contacts at the cam springs or otherwise, obviously, the operation of the register sender would cease and no connection would be established. The calling subscriber being unaware of this condition would continue to dial the whole number and then await the response of the called subscriber. He would hear no ring-back tone which would signify that the desired subscriber was not being signalled, and if he continued to keep his receiver off the switch-hook, again the regis-

ter sender would be released and the attendant would be signalled.

*Selector and connector modifications—
power driven*

The automatic switches described above, designed in accordance with the general object of this invention, are all of the type in which the switch wipers are moved from one set of contacts to the next set of contacts by a stepping magnet, this method of operation being known as the step-by-step method. The circuits of these switches however are readily adaptable for controlling power driven switches, in which the shaft carrying the wipers is rotated by a gear attached thereto engaging a pinion fastened to a constantly rotating shaft. In Fig. 6, a selector and a connector are shown adapted for power drive, and their operation as far as it differs from the operation of the step-by-step operated selector and connector described above, will now be given, noting that similar parts of the two types of selectors and connectors have been labeled correspondingly, the designations differing only in the hundreds digit (to correspond with the figure number).

Considering first the mechanical construction of the selector S³ in so far as it differs from that of a selector S' previously described, on the shaft carrying cams 620 and 621 and the switch wipers 631-633, inclusive, the flexible gear 687 is mounted. This flexible gear 687 is adapted to engage the teeth of the pinion 689 fastened to the constantly rotating shaft 690 (only a section of which has been shown). Normally the flexible gear 687 is held out of engagement with the pinion 689 against the stop 688 by armature 691 of control magnet 608 under the tension of spring 692.

The operation of selector S³ is the same as that of selector S' or S², except that line relay 606, in operating, instead of closing a self-interrupting circuit for a stepping magnet, closes a direct circuit for control magnet 608. Magnet 608 energizes and by attracting the armature 691 against the force of the spring 692, the teeth of the flexible gear 687 are permitted to engage the teeth of the pinion 689. The shaft carrying the switch wipers and the cams 320 and 321 then rotates as long as the pinion 689 and gear 687 are engaged, which condition exists until the switch wiper finds an idle trunk in a selected group, the circuit of magnet 608 being reestablished after the proper group has been selected and line relay 606 has deenergized from ground potential encountered by the test wiper 633 (or 634) in passing over test contacts representing busy trunks. As soon as an idle trunk line is reached, no ground potential will be present on the bank contact engaged by test wiper and consequently the circuit for magnet 608 will be opened. Magnet 608 im-

mediately deenergizes, allowing its armature 691 to disengage the flexible gear from the pinion 689 under the force of spring 692. Consequently the switch wipers are arrested 5 in this position in engagement with the bank contacts of the idle trunk line.

When the selector S^3 is released at the end of a call, magnet 608 is again energized, the same as is the stepping magnet of selectors S' or S^2 , from ground at cam springs 623. Again magnet 608, in operating, permits the flexible gear 687 to engage the pinion 689. Switch wipers are then rotated until they are again in their normal position whereupon 15 cam springs 623 separate and opens the circuit of magnet 608. Magnet 608, in deenergizing, again permits armature 691 to disengage the flexible gear 687 from the pinion 689, and thus arrests the switch wipers in their 20 normal position.

The mechanical arrangement of the connector C' is similar to that of the selector S^3 except that a gear shifting arrangement has been added so that the switch wiper shaft is 25 rotated at one speed when the wipers are being rotated to the proper group, and are rotated at a much slower speed when the wipers are selecting the proper set of contacts in that group. A third cam 621² having the 30 cam springs 624² has also been added. In this case the constantly rotating shaft 690' carries two pinions, 689' and 695', pinion 689' being considerably larger than pinion 695'. An auxiliary shaft 694 is provided upon 35 which are mounted gears 695, 693, and 693'. The shaft 694 is movable axially under the control of armature 696 of control magnet 697, its normal position being as shown with the armature 696 against the stop 696' under the 40 tension of the spring 692². In this position the gear 693 meshes with the pinion 689'. When the magnet 697 is operated, the shaft 694 is moved to its alternative position, in which position gear 693' engages pinion 695'. 45 In either position of the shaft 694 the idler gear 699 engages gear 695. The flexible gear 687' corresponds with the flexible gear 687 of the selector S^3 and is arranged to engage the teeth of gear 699, being normally held out of 50 engagement therewith up against the stop 688' by armature 691' under the tension of springs 692'. The added cam 621² controls the cam springs 624² in such a manner that these springs are closed except when the 55 switch wipers are centered on a set of bank contacts; that is, as soon as the switch wipers are moved off of a set of bank contacts, springs 624² are closed and remain closed until the switch wipers are moved well onto the next set of bank contacts. It should also be noted that in the connector C' , the relay corresponding 60 to relay 459' of the connector C is eliminated.

The operation of the connector C' is substantially like that of connector C with a few

exceptions which may now be pointed out and described. When line relay 657 operates, it closes a direct circuit at armature 673 for control magnet 608' which in operating its armature 691' permits the flexible gear 687' to engage the rotating idle gear 699. The shaft carrying the cams 620', 621' and 621², and the switch wipers is then rotated continuously until the wipers engage the first set of bank contacts of the proper group, corresponding to the wiper setting of the third digit register. As will be remembered from the description of the operation of connector C ; the control circuit is opened at the register sender as the wipers move over the last five contacts of the group preceding the desired group, so that line relay 657 falls back when the wipers engage the first set of contacts of the desired group, and in deenergizing, opens the circuit of magnet 608'. Magnet 608' thereupon deenergizes, and by releasing its armature 691', causes the flexible gear 687' to be disengaged from the gear 699, so the wipers are arrested in this position.

Line relay 657, in deenergizing, also disconnects itself from the control circuit by the release of armature 671, and includes control relay 659 therein by releasing armature 672 (remembering relay 656 is operated at this time). When the control circuit is again closed at the register sender, following the registration of the next digit, control relay 659 is operated. This relay performs the functions of both relays 495 and 495' of connector C . At armature 677 the busy test circuit is prepared. At armature 678 a circuit is prepared for controlling the operation of the impulsing relay as will be described presently. At armature 679 the circuit of magnet 697 is closed, and at armature 679' another circuit for magnet 608' is prepared. Magnet 697, by attracting its armature 696, moves the shaft 694 axially so that gear 693' is moved into engagement with pinion 695' and gear 693 is moved out of engagement with gear 689'. Since the pinion 695' is much smaller than pinion 689', and gear 693' is much larger than gear 693, the speed of rotation of gear 695 and the idler gear 699 is greatly reduced. A further result of the energization of magnet 697 is the closure of another circuit for magnet 608' at armature 698. Magnet 608' again energizes and permits the flexible gear 687' to engage gear 699. The switch wipers are now rotated over the contacts of the selected group but at a much slower speed than at which they were rotated previously. As soon as the wipers are moved off the first set of bank contacts, cam springs 624² are closed, closing a local circuit for relay 659, at the same time short-circuiting the impulsing relay in the register sender. When the wipers are moved into engagement with the second set of bank contacts in the selected group, which set terminates the first sub-

scriber's line of the group, cam springs 624² open and the short circuit is again removed and the impulsing relay in the register sender is again energized. This operation continues until the marking relays of the register sender, controlled by the impulsing relay as previously described, have connected ground potential to the marking conductor connected to the contact with which the last 10 digit register wiper is in engagement. When this takes place, the control circuit is opened in the register sender by the operation of the stop relay as previously described, so that when the switch wipers are moved into engagement with the next set of bank contacts, corresponding to the wiper setting of the last 15 digit register, and cam springs 624² open, the circuit of relay 659 is interrupted. This relay then deenergizes and immediately opens the circuit of magnet 608' at armature 679 and also opens the circuit of magnet 697 at armature 679'. When magnet 608' deenergizes and releases its armature 691', the flexible gear 687' is disengaged from the gear 20 699, and the switch wipers are brought to rest in engagement with the proper set of bank contacts. The deenergization of magnet 697 causes the shaft 694 to be shifted back to its normal position under the tension of 25 springs 692².

When the connector C' is released at the end of a call, magnet 608' is again energized, the same as is the stepping magnet of the connector C, from ground at cam spring 623'. Again magnet 608' in operating, permits the flexible gear 687' to engage the idler gear 699, now again rotating at its higher speed. The switch wipers are then rotated until they are again in their normal position whereupon 30 cam springs 623' separate and open the circuit of magnet 608'. Magnet 608', in deenergizing, again permits armature 691' to disengage the flexible gear 687' from the idler gear 699, and thus arrest the switch wipers in 35 their normal position.

It should be obvious from the foregoing description that the reverting call switch RV could also be modified easily to be operated by the power driven method, by changing its 40 control circuits to correspond with those of connector C' and by providing the same kind of driving and gear shifting mechanism.

This completes the description of the operation of the invention, what is thought new 45 and is desired to have protected by Letters Patent will be pointed out in the appended claims.

What is claimed is:

1. In a telephone system, an automatic 50 switch having access to groups of lines, a register controller, a circuit between the said switch and said register controller over which the switch is controlled to select a desired group, means for opening said circuit while 55 the switch is passing the group preceding the

group wanted, and a local circuit for continuing the movement of the switch to the wanted group.

2. In a telephone system, an automatic switch having access to groups of lines, a register controller for causing said switch to select a desired group, means for removing said switch from the control of the register controller while the switch is associated with the group preceding the wanted group, and 60 means for automatically continuing the selecting movement of the switch until the desired group is reached.

3. In a telephone system, a trunk line terminating in an automatic switch, a relay in 65 said switch, means for advancing the switch over its bank contacts responsive to the energization of said relay, a circuit for energizing said relay over a conductor of said trunk line, and a local circuit controlled by the switch 70 for maintaining said relay energized.

4. A system as claimed in claim 3 in which the energization of the relay over the local circuit causes the switch to pass over a plurality of contacts in order to reach a desired 75 group of contacts.

5. In a telephone system, a selector, trunks arranged in groups accessible in the banks of said selector, a controlling mechanism, means for setting said controlling mechanism in accordance with a number, means in said controlling mechanism for closing a loop across the talking conductors of said selector to start the movement of the wipers of said selector over their bank contacts, means in said selector for sending an impulse to said controlling mechanism each time the wipers pass the contacts of one group, means in said controlling device responsive to said impulses for opening said loop when the number of impulses sent back equals said first number, and means in said selector for continuing the movement of said wipers to the next group until they engage the contacts terminating an idle trunk.

6. In an automatic system, a single motion selector switch, a plurality of groups of trunks accessible in the banks of said switch, a pair of conductors terminating in said switch, a register for registering the digits of called telephone numbers, means in said register operable when one digit of a number is registered for closing a loop across said pair of conductors, means in said selector operative responsive to the closure of said loop for starting the movement of the wipers of said switch over their bank contacts, means in said register sender for opening said loop while the wipers of said selector are moving over the contacts terminating the group of trunk preceding the group corresponding to the said one digit, and means for continuing the movement of the wipers of said switch until they engage the contacts terminating the first idle 100

trunk of the group corresponding to the said one digit.

7. In a telephone system, a connector, lines arranged in groups accessible in the banks of said connector, a register controller and means for registering two digits thereon, means for associating said register controller with said connector, means in said register controller for closing a loop across the talking conductors of said connection to start the movement of the wipers of said connector over their bank contacts, means in said connector for sending an impulse to said register controller each time the wipers pass over the contacts of a group and for continuing the movement of said wipers until they reach the first contact of the succeeding group, means in said register controller for opening said loop operative when the number of impulses sent to said register controller equals the first of said digits, means in said register controller for again closing said loop to again start the movement of the wipers of said connector, and means in said connector then operative to send an impulse to said register controller each time the wipers pass over a contact and for continuing the movement of said wipers until they reach the succeeding contact, the means in said register controller for opening said loop again operating when the number of impulses sent to said register controller equals the second of said digits.

8. In combination, an automatic switch having two selecting movements in the same direction, a register sender, a circuit extending between the switch and register sender over which the former is revertively controlled, a cam operated by the switch for sending impulses over said circuit during one selecting movement, and a relay in said switch for sending impulses over said circuit during the other selecting movement.

9. In a telephone system, party lines, automatic switches for extending connections to said lines, a plurality of sources of signalling current, a register sender for registering a called line number and for controlling the operation of said switches to select the line corresponding to the number registered, and means in said register sender for selecting the proper signalling current to signal a desired party on the called party line.

10. In an automatic telephone system, subscribers' lines, automatic switches for extending connections to said lines, a register sender for registering a called line number and for controlling the operation of said switches to select the line corresponding to the number registered, and means in said register sender for signalling the called subscriber.

11. In an automatic telephone system, subscribers' lines, automatic switches for extending connections to said lines, a register sender for registering a called line number and for controlling the operation of said switches to

select the line corresponding to the number registered, means in said register sender for signalling the called subscriber, and means controlled by the response of the called subscriber for releasing the register sender.

12. In an automatic telephone system, subscribers' lines, automatic switches for extending connections to said lines, a register sender for registering a called line number and for controlling the operation of said switches to select the line corresponding to the number registered, and means in said register sender for testing whether the selected line is busy or idle.

13. In an automatic telephone system, subscribers' lines, automatic switches for extending connections to said lines, a register sender for registering a called line number and for controlling the operation of said switches to select the line corresponding to the number registered, means in said register sender for testing whether the selected line is busy or idle, and means in said register sender operable if the selected line tests idle for signalling the called subscriber.

14. In a telephone system, a calling subscriber's line, a called subscriber's line, an automatic switch having access to said called line, a register sender, means for associating said register with the calling line, means for registering the number of the called line on said register sender, means controlled by said register sender for operating said switch to select said called line, testing means in said register sender for testing said called line, and means controlled by said testing means for disassociating said register sender from the calling line when said called line tests busy.

15. In a telephone system, a calling subscriber's line, a called subscriber's line, an automatic switch having access to said called line, a register sender, means for associating said register sender with the calling line, means for registering the number of the called line on said register sender, means controlled by said register sender for operating said switch to select said called line, testing means in said register sender for testing said called line, means controlled by said testing means for disassociating said register sender from the calling line when said called line tests busy.

16. In a telephone system, a calling subscriber's line, a called subscriber's line, an automatic switch having access to said called line, a register sender, means for associating said register sender with the calling line, means for registering the number of the called line on said register sender, means controlled by said register sender for operating said switch to select said called line, testing means in said register sender for testing said called line.

- line, means controlled by said testing means for disassociating said register sender from the calling line when said called line tests busy, means in said register sender operable when the called line tests idle for signalling the called subscriber, and means operable when the called subscriber answers for disassociating said register sender from said calling line. 5
17. In a telephone system, subscribers' lines, an automatic switch for extending connections to said lines, a register controller for registering a called line number and for controlling the operation of said switch to select a line in accordance with the called number registered, means in said switch for testing whether the selected line is busy or idle, and means in said register controller controlled by said first means for releasing said register controller in case the selected line tests busy. 10
18. In a telephone system, subscribers' lines, an automatic switch for extending connections to said lines, a register controller for registering a called line number and for controlling the operation of said switch to select a line in accordance with the called number registered, means in said switch for testing whether the selected line is busy or idle, and means in said register controller for automatically signalling the called subscriber in case the selected line tests idle. 15
19. In a telephone system, subscribers' lines, an automatic switch having access to said lines, a magnet in said switch for operating the same, a register controller for registering a called line number and for controlling the operation of said switch to select the line corresponding to the number registered, testing means in said switch for testing the selected line, said last means operating when the selected line tests busy to connect said magnet to a talking conductor of said switch, and means in said register controller operative responsive to the connection of said magnet to a talking conductor of said switch for releasing said register controller. 20
20. In a telephone system, subscribers' lines, an automatic switch having access to said lines, a register controller for registering a called line number and for controlling the operation of said switch to select the line corresponding to the number registered, testing means in said switch for testing the selected line, said last means operating when the selected line tests busy to connect a source of potential to a talking conductor of said switch, and means in said register controller operative responsive to the connection of said source of potential to a talking conductor of said switch for releasing said register controller. 25
21. In a telephone system, a plurality of lines, each line having a cut-off relay, a connector having access to said lines, a trunk terminating in said switch, means for oper- 30
- ating said connector to select one of said lines, a switching relay for connecting said trunk with the selected line, a test relay for testing the selected line for the busy or idle condition, means for operating said switching relay in series with said test relay when the selected line is found busy, and means for operating said switching relay in series with the cut-off relay of the selected line when the selected line is found idle. 70
22. In a telephone system, automatic switches for setting up connections to two different trunk lines, a register sender for controlling said switches, a relay in said register sender for releasing the same, means for operating said relay whenever either trunk line is connected with, and means associated with one of said trunk lines for delaying the release of the register sender responsive to the energization of said relay. 75
23. In a telephone system, means including a trunk line and automatic switches for setting up connections, a register sender associated with said trunk line for controlling said switches, condensers associated with the talking conductors of said trunk line, and means in said register sender for determining whether or not the said condensers are included in said talking conductors when a connection is established. 80
24. In a telephone system, a trunk line, a register sender, means for associating said register sender with said trunk, means including a circuit for maintaining said register sender associated with said trunk line, means operative a predetermined interval after the association of said register sender with said trunk line for establishing a different current flow in said circuit, and means responsive to said change in current flow in said circuit for disassociating said register sender from said trunk line. 85
25. In a telephone system, a trunk line, a register sender, means for associating said register sender with said trunk, means including a circuit for maintaining said register sender associated with said trunk line, means operative a predetermined interval after the association of said register sender with said trunk line for changing the current flow in said circuit, means responsive to said change in current flow in said circuit for disassociating said register sender from said trunk line and for connecting a source of current of a distinctive character on a conductor of said trunk line. 90
26. In a telephone system, an automatic switch having access to groups of trunk lines terminating in other automatic switches, a register controller for registering a called number and for controlling the operation of said switch to select a desired group, means in said switch for selecting an idle trunk in the selected group providing one is available, said register controller being also for con- 95

trolling the operation of the switch terminating the selected idle trunk, and means at said first automatic switch for causing said register controller to operate just as though an idle trunk had been found and for releasing said register controller and for giving the calling subscriber a busy tone providing no idle trunk is available in the desired group.

5 27. In a telephone system, a train of automatic switches for extending a calling line, means in each switch for controlling its operation and release and for establishing a talking connection to the wipers when in set position, said means consisting solely of re-
lays and excluding any progressively movable sequence switches, a register sender for determining the extent of operation of said switches, and means whereby said switches are controlled by said register sender according to the revertive system of control.

10 28. In a telephone system, a train of automatic switches for extending a connection from a calling line, each switch comprising a bank of contacts and associated wipers together with a stepping mechanism for advancing the wipers, a register sender for receiving the called number and for controlling said switches in accordance therewith, and means in each switch for controlling said 15 register sender so that the switches are operated according to the revertive system of control.

15 29. In a telephone system, a train of automatic switches for setting up a connection from a calling line, a register sender for receiving the called number and controlling said switches in accordance therewith, means in each switch for controlling said register sender so that the switches are operated on 20 the revertive control system, a release trunk conductor extending serially through said train of switches, and means in one of said switches for connecting a current source to said conductor to maintain the remaining switches in operated position.

25 In witness whereof, I hereunto subscribe my name this 4th day of January, A. D. 1927.

JOHN WICKS.
